CONTROL APPARATUS FOR STARTING, STOPPING, RUNNING, AND
REVERSING AN INTERNAL-COMBUSTION ENGINE
Filed April 26, 1949

Filed April 26, 1949

<img alt="A detailed technical diagram of a marine engine control system, labeled Fig. 1 and Fig. 2. The diagram shows a complex network of control pipes, valves, and pressure regulating components. It includes labels for 'Ahead', 'Astern', 'Full Speed', 'Run & Idle', and 'Stop' positions. Various valves are numbered (e.g., 10, 11, 12, 13, 14, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 499, 500, 501, 502, 503, 504, 505, 506, 507, 508, 509, 510, 511, 512, 513, 514, 515, 516, 517, 518, 519, 520, 521, 522, 523, 524, 525, 526, 527, 528, 529, 529, 530, 531, 532, 533, 534, 535, 536, 537, 538, 539, 540, 541, 542, 543, 544, 545, 546, 547, 548, 549, 550, 551, 552, 553, 554, 555, 556, 557, 558, 559, 560, 561, 562, 563, 564, 565, 566, 567, 568, 569, 570, 571, 572, 573, 574, 575, 576, 577, 578, 579, 579, 580, 581, 582, 583, 584, 585, 586, 587, 588, 589, 589, 590, 591, 592, 593, 594, 595, 596, 597, 598, 599, 599, 600, 601, 602, 603, 604, 605, 606, 607, 608, 609, 609, 610, 611, 612, 613, 614, 615, 616, 617, 618, 619, 619, 620, 621, 622, 623, 624, 625, 626, 627, 628, 629, 629, 630, 631, 632, 633, 634, 635, 636, 637, 638, 639, 639, 640, 641, 642, 643, 644, 645, 646, 647, 648, 649, 649, 650, 651, 652, 653, 654, 655, 656, 657, 658, 659, 659, 660, 661, 662, 663, 664, 665, 666, 667, 668, 669, 669, 670, 671, 672, 673, 674, 675, 676, 677, 678, 679, 679, 680, 681, 682, 683, 684, 685, 686, 687, 688, 689, 689, 690, 691, 692, 693, 694, 695, 696, 697, 698, 699, 699, 700, 701, 702, 703, 704, 705, 706, 707, 708, 709, 709, 710, 711, 712, 713, 714, 715, 716, 717, 718, 719, 719, 720, 721, 722, 723, 724, 725, 726, 727, 728, 729, 729, 730, 731, 732, 733, 734, 735, 736, 737, 738, 739, 739, 740, 741, 742, 743, 744, 745, 746, 747, 748, 749, 749, 750, 751, 752, 753, 754, 755, 756, 757, 758, 759, 759, 760, 761, 762, 763, 764, 765, 766, 767, 768, 769, 769, 770, 771, 772, 773, 774, 775, 776, 777, 778, 779, 779, 780, 781, 782, 783, 784, 785, 786, 787, 788, 789, 789, 790, 791, 792, 793, 794, 795, 796, 797, 798, 799, 799, 800, 801, 802, 803, 804, 805, 806, 807, 808, 809, 809, 810, 811, 812, 813, 814, 815, 816, 817, 818, 819, 819, 820, 821, 822, 823, 824, 825, 826, 827, 828, 829, 829, 830, 831, 832, 833, 834, 835, 836, 837, 838, 839, 839, 840, 841, 842, 843, 844, 845, 846, 847, 848, 849, 849, 850, 851, 852, 853, 854, 855, 856, 857, 858, 859, 859, 860, 861, 862, 863, 864, 865, 866, 867, 868, 869, 869, 870, 871, 872, 873, 874, 875, 876, 877, 878, 879, 879, 880, 881, 882, 883, 884, 885, 886, 887, 888, 889, 889, 890, 891, 892, 893, 894, 895, 896, 897, 898, 899, 899, 900, 901, 902, 903, 904, 905, 906, 907, 908, 909, 909, 910, 911, 912, 913, 914, 915, 916, 917, 918, 919, 919, 920, 921, 922, 923, 924, 925, 926, 927, 928, 929, 929, 930, 931, 932, 933, 934, 935, 936, 937, 938, 939, 939, 940, 941, 942, 943, 944, 945, 946, 947, 948, 949, 949, 950, 951, 952, 953, 954, 955, 956, 957, 958, 959, 959, 960, 961, 962, 963, 964, 965, 966, 967, 968, 969, 969, 970, 971, 972, 973, 974, 975, 976, 977, 978, 979, 979, 980, 981, 982, 983, 984, 985, 986, 987, 988, 989, 989, 990, 991, 992, 993, 994, 995, 996, 997, 998, 999, 999, 1000, 1001, 1002, 1003, 1004, 1005, 1006, 1007, 1008, 1009, 1009, 1010, 1011, 1012, 1013, 1014, 1015, 1016, 1017, 1018, 1019, 1019, 1020, 1021, 1022, 1023, 1024, 1025, 1026, 1027, 1028, 1029, 1029, 1030, 1031, 1032, 1033, 1034, 1035, 1036, 1037, 1038, 1039, 1039, 1040, 1041, 1042, 1043, 1044, 1045, 1046, 1047, 1048, 1049, 1049, 1050, 1051, 1052, 1053, 1054, 1055, 1056, 1057, 1058, 1059, 1059, 1060, 1061, 1062, 1063, 1064, 1065, 1066, 1067, 1068, 1069, 1069, 1070, 1071, 1072, 1073, 1074, 1075, 1076, 1077, 1078, 1079, 1079, 1080, 1081, 1082, 1083, 1084, 1085, 1086, 1087, 1088, 1089, 1089, 1090, 1091, 1092, 1093, 1094, 1095, 1096, 1097, 1098, 1099, 1099, 1100, 1101, 1102, 1103, 1104, 1105, 1106, 1107, 1108, 1109, 1109, 1110, 1111, 1112, 1113, 1114, 1115, 1116, 1117, 1118, 1119, 1119, 1120, 1121, 1122, 1123, 1124, 1125, 1126, 1127, 1128, 1129, 1129, 1130, 1131, 1132, 1133, 1134, 1135, 1136, 1137, 1138, 1139, 1139, 1140, 1141, 1142, 1143, 1144, 1145, 1146, 1147, 1148, 1149, 1149, 1150, 1151, 1152, 1153, 1154, 1155, 1156, 1157, 1158, 1159, 1159, 1160, 1161, 1162, 1163, 1164, 1165, 1166, 1167, 1168, 1169, 1169, 1170, 1171, 1172, 1173, 1174, 1175, 1176, 1177, 1178, 1179, 1179, 1180, 1181, 1182, 1183, 1184, 1185, 1186, 1187, 1188, 1189, 1189, 1190, 1191, 1192, 1193, 1194, 1195, 1196, 1197, 1198, 1199, 1199, 1200, 1201, 1202, 1203, 1204, 1205, 1206, 1207, 1208, 1209, 1209, 1210, 1211, 1212, 1213, 1214, 1215, 1216, 1217, 1218, 1219, 1219, 1220, 1221, 1222, 1223, 1224, 1225, 1226, 1227, 1228, 1229, 1229, 1230, 1231, 1232, 1233, 1234, 1235, 1236, 1237, 1238, 1239, 1239, 1240, 1241, 1242, 1243, 1244, 1245, 1246, 1247, 1248, 1249, 1249, 1250, 1251, 1252, 1253, 1254, 1255, 1256, 1257, 1258, 1259, 1259, 1260, 1261, 1262, 1263, 1264, 1265, 1266, 1267, 1268, 1269, 1269, 1270, 1271, 1272, 1273, 1274, 1275, 1276, 1277, 1278, 1279, 1279, 1280, 1281, 1282, 1283, 1284, 1285, 1286, 1287, 1288, 1289, 1289, 1290, 1291, 1292, 1293, 1294, 1295, 1296, 1297, 1298, 1299, 1299, 1300, 1301, 1302, 1303, 1304, 1305, 1306, 1307, 1308, 1309, 1309, 1310, 1311, 1312, 1313, 1314, 1315, 1316, 1317, 1318, 1319, 1319, 1320, 1321, 1322, 1323, 1324, 1325, 1326, 1327, 1328, 1329, 1329, 1330, 1331, 1332, 1333, 1334, 1335, 1336, 1337, 1338, 1339, 1339, 1340, 1341, 1342, 1343, 1344, 1345, 1346, 1347, 1348, 1349, 1349, 1350, 1351, 1352, 1353, 1354, 1355, 1356, 1357, 1358, 1359, 1359, 1360, 1361, 1362, 1363, 1364, 1365, 1366, 1367, 1368, 1369, 1369, 1370, 1371, 1372, 1373, 1374, 1375, 1376, 1377, 1378, 1379, 1379, 1380, 1381, 1382, 1383, 1384, 1385, 1386, 1387, 1388, 1389, 1389, 1390, 1391, 1392, 1393, 1394, 1395, 1396, 1397, 1398, 1399, 1399, 1400, 1401, 1402, 1403, 1404, 1405, 1406, 1407, 1408, 1409, 1409, 1410, 1411, 1412, 1413, 1414, 1415, 1416, 1417, 1418, 1418, 1419, 1420, 1421, 1422, 1423, 1424, 1425, 1426, 1427, 1428, 1429, 1429, 1430, 1431, 1432, 1433, 1434, 1435, 1436, 1437, 1438, 1439, 1439, 1440, 1441, 1442, 1443, 1444, 1445, 1446, 1447, 1448, 1449, 1449, 1450, 1451, 1452, 1453, 1454, 1455, 1456, 1457, 1458, 1459, 1459, 1460, 1461, 1462, 1463, 1464, 1465, 1466, 1467, 1468, 1469, 1469, 1470, 1471, 1472, 1473, 1474, 1475, 1476, 1477, 1478, 1479, 1479, 1480, 1481, 1482, 1483, 1484, 1485, 1486, 1487, 1488, 1489, 1489, 1490, 1491, 1492, 1493, 1494, 1495, 1496, 1497, 1498, 1499, 1499, 1500, 1501, 1502, 1503, 1504, 1505, 1506, 1507, 1508, 1509, 1509, 1510, 1511, 1512, 1513, 1514, 1515, 1516, 1517, 1518, 1518, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1559, 1559, 1560, 1561, 1562, 1563, 1564, 1565, 1566, 1567, 1568, 1569, 1569, 1570, 1571, 1572, 1573, 1574, 1575, 1576, 1577, 1578, 1579, 1579, 1580, 1581, 1582, 1583, 1584, 1585, 1586, 1587, 1588, 1589, 1589, 1590, 1591, 1592, 1593, 1594, 1595, 1596, 1597, 1598, 1599, 1599, 1600, 1601, 1602, 1603, 1604, 1605, 1606, 1607, 1608, 1609, 1609, 1610, 1611, 1612, 1613, 1614, 1615, 1616, 1617, 1618, 1618, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1659, 1659, 1660, 1661, 1662, 1663, 1664, 1665, 1666, 1667, 1668, 1669, 1669, 1670, 1671, 1672, 1673, 1674, 1675, 1676, 1677, 1678, 1679, 1679, 1680, 1681, 1682, 1683, 1684, 1685, 1686, 1687, 1688, 1689, 1689, 1690, 1691, 1692, 1693, 1694, 1695, 1696, 1697, 1698, 1699, 1699, 1700, 1701, 1702, 1703, 1704, 1705, 1706, 1707, 1708, 1709, 1709, 1710, 1711, 1712, 1713, 1714, 1715, 1716, 1717, 1718, 1718, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741, 1742, 1743, 1744, 1745, 1746, 1747, 1748, 1749, 1749, 1750, 1751, 1752, 1753, 1754, 1755, 1756, 1757, 1758, 1759, 1759, 1760, 1761, 1762, 1763, 1764, 1765, 1766, 1767, 1768, 1769, 1769, 1770, 1771, 1772, 1773, 1774, 1775, 1776, 1777, 1778, 1779, 1779, 1780, 1781, 1782, 1783, 1784, 1785, 1786, 1787, 1788, 1789, 1789, 1790, 1791, 1792, 1793, 1794, 1795, 1796, 1797, 1798, 1799, 1799, 1800, 1801, 1802, 1803, 1804, 1805, 1806, 1807, 1808, 1809, 1809, 1810, 1811, 1812, 1813, 1814, 1815, 1816, 1817, 1818, 1818, 1819, 1820, 1821, 1822, 1823, 1824, 1825, 1826, 1827, 1828, 1829, 1829, 1830, 1831, 1832, 1833, 1834, 1835, 1836, 1837, 1838, 1839, 1839, 1840, 1841, 1842, 1843, 1844, 1845, 1846, 1847, 1848, 1849, 1849, 1850, 1851, 1852, 1853, 1854, 1855, 1856, 1857, 1858, 1859, 1859, 1860, 1861, 1862, 1863, 1864, 1865, 1866, 1867, 1868, 1869, 1869, 1870, 1871, 1872, 1873, 1874, 1875, 1876, 1877, 1878, 1879, 1879, 1880, 1881, 1882, 1883, 1884, 1885, 1886, 1887, 1888, 1889, 1889, 1890, 1891, 1892, 1893, 1894, 1895, 1896, 1897, 1898, 1899, 1899, 1900, 1901, 1902, 1903, 1904, 1905, 1906, 1907, 1908, 1909, 1909, 1910, 1911, 1912, 1913, 1914, 1915, 1916, 1917, 1918, 1918, 1919, 1920, 1921, 1922, 1923, 1924, 1925, 1926, 1927, 1928, 1929, 1929, 1930, 1931, 1932, 1933, 1934, 1935, 1936, 1937, 1938, 1939, 1939, 1940, 1941, 1942, 1943, 1944, 1945, 1946, 1947, 1948, 1949, 1949, 1950, 1951, 1952, 1953, 1954, 1955, 1956, 1957, 1958, 1959, 1959, 1960, 1961, 1962, 1963, 1964, 1965, 1966, 1967, 1968, 1969, 1969, 1970, 1971, 1972, 1973, 1974, 1975, 1976, 1977, 1978, 1979, 1979, 1980, 1981, 1982, 1983, 1984, 1985, 1986, 1987, 1988, 1989, 1989, 1990, 1991, 1992, 1993, 1994, 1995, 1996, 1997, 1998, 1999, 1999, 2000, 2001, 2002, 2003, 2004, 2005, 2006, 2007, 2008, 2009, 2009, 2010, 2011, 2012, 2013, 2014, 2015, 2016, 2017, 2018, 2018, 2019, 2020, 2021, 2022, 2023, 2024, 2025, 2026, 2027, 2028, 2029, 2029, 2030, 2031, 2032, 2033, 2034, 2035, 2036, 2037, 2038, 2039, 2039, 2040, 2041, 2042, 2043, 2044, 2045, 2046, 2047, 2048, 2049, 2049, 2050, 2051, 2052, 2053, 2054, 2055, 2056, 2057, 2058, 2059, 2059, CONTROL APPARATUS FOR STARTING,
STOPPING, RUNNING, AND REVERS-
ING AN INTERNAL-COMBUSTION EN-
GINERaymond E. Miller, Wilkinsburg, Pa., assignor to
Westinghouse Air Brake Company, a corpora-
tion of Pennsylvania

Application April 26, 1949, Serial No. 89,702

14 Claims. (Cl. 60—16)

1

This invention relates to engine control apparatus and more particularly to fluid pressure control apparatus for controlling the starting, stopping, running, reversing, etc., of such as a reversible Diesel engine.

One of the objects of the invention is the provision of improved control apparatus for effecting the above operations concerned with operating a reversible Diesel engine.

Another object of the invention is the provision of improved means for effecting cut-off of supply of starting air to the engine automatically upon running of said engine on fuel.

Still another object of the invention is the provision of means for preventing an over supply of fuel in starting an engine having a fuel pressure regulating control shaft operatively connected to the usual fuel control shaft in such a manner that in time of starting the fuel control valve will be wide open with fuel pressure at a minimum value.

Other objects and advantages will become apparent from the following more detailed description of the invention.

In the accompanying drawing; Fig. 1 is a schematic view, partly in outline and partly in section of a control apparatus embodying the invention; and Fig. 2 is a cross-sectional view of a valve device, three of which are shown symbolically, comprised in the control apparatus shown in Fig. 1.

Description

The reversible engine (not shown) may comprise the usual crank shaft 1, only a portion of which is shown in the drawing, and a cam shaft 2, a portion of which is shown also in the drawing. The crank shaft 1 may be operably connected to the pistons (not shown) of the engine and operatively connected to a propeller or propellers (not shown) of a ship, for example. The cam shaft 2 is adapted to be driven in proper phase with the crank shaft 1 in the usual manner for operating conventional engine valve mechanism (not shown) to permit the engine to be started by compressed air for operation in either direction of rotation, to, for instance, drive a ship ahead or astern. The cam shaft 2 may have the usual forward cams (not shown), to provide for operation in one or an ahead direction and may have the usual reverse cams (not shown) to provide for operation in the reverse or astern direction. In the well known manner the cam shaft 2 may be shiftable axially in one direction to a position for rendering

the forward cams effective to operate the engine's valve or timing gear, and in the opposite direction to another position for rendering the reverse cams effective to operate said gear.

5 The reversible internal combustion engine may further comprise a fuel control shaft 3 operatively connected to fuel control valve means (not shown) for regulating the fuel flow area and thereby affecting regulation of the quantity of fuel supplied to the engine cylinders by way of fuel injection nozzles or the like (not shown). The control shaft 3 is secured for turning movement by a fuel control lever 4 which may be disposed outside the engine. The lever 4 is adapted to be moved to a "Fuel Off" position, indicated by dot and dash line so titled in the drawing, in which position the fuel control valve means is so conditioned as to cut off supply of fuel to the engine's cylinders. By counter-clockwise turning movement of lever 4, as viewed in the drawing, from its "Fuel Off" position to a "Full Fuel" position, the fuel flow area may be increased up to a maximum amount corresponding to said "Full Fuel" position.

10 Still further, the internal combustion engine may comprise a fuel pressure regulation control shaft 4a operatively connected to fuel pressure regulating means on the engine (not shown). The shaft 4a is adapted to be moved to and between opposite "Maximum Fuel Pressure" and "Minimum Fuel Pressure" positions to cause a corresponding regulation of the pressure of fuel supplied to the engine, hence to a certain extent, the amount of fuel to be supplied to the engine for a given position of the fuel control shaft 3.

15 The control apparatus embodying the invention may comprise a speed governor device 5 operable in the usual manner through a driven connection with the crank shaft 1 to control position of the fuel control shaft 3, hence the amount of fuel supplied to the engine, and thereby its power or speed through positioning of the fuel control lever 4 in accord with the speed setting of said governor device. An actuator in the form of a speed control cylinder device 6 is arranged to control the speed setting of the governor device 5.

20 In a well known manner, the pressure of fluid in the speed control cylinder device 6 may be varied from a station remote from the engine, such as in the pilot house of a ship by means such as a self-lapping speed control valve device (not shown) comprised in an operator's control device 8 located at such a station. A

speed control pipe 9 is provided to convey fluid under pressure between the operator's control device 8 in the pilot house and the speed control cylinder device 6 at the engine.

According to a feature of the invention, I provide an extendable resilient link assemblage 7 arranged to connect the fuel pressure regulation control shaft 4a with the fuel control shaft 3, so that normally the former will move with the latter during operation of the engine, but during starting of the engine, as will be pointed out hereinafter, the pressure regulation control shaft 4a may be moved to its "Minimum Fuel Pressure" position, while the fuel control shaft 3 may remain stationary.

To condition the engine for operation in one direction or the other, the control apparatus is provided with the usual cam shift cylinder device 10 mounted on or near the engine and operatively connected to the cam shaft 2 for shifting position of same according as whether it is desired to operate the engine in one direction of rotation for propelling the ship ahead, for example, or to operate the engine in the opposite direction of rotation for propelling the ship astern. The cam shift cylinder 10 is arranged to be controlled by the operator's control device 8 in the pilot house according to pressure conditions established by said device 8 in ahead and astern control pipes 11 and 12, respectively, which extend between said device 8 in the pilot house to the engine remote therefrom.

A fluid pressure operated fuel cut-off cylinder device 17 is provided for effecting cut-off of fuel to the engine on stopping or reversing same. A directional interlock device 18 is adapted and arranged to modify control of operation of the fuel cut-off cylinder device 17, as will be described in detail hereinafter, according to direction of rotation of the engine crank shaft 1.

A relay valve device 19 and double check valve devices 19a, 19b are provided, arranged to control operation of the fuel cut-off cylinder device 17.

A starting air control valve device 20 is provided for controlling supply of starting air to the engine. A starting interlock device 21 is arranged to control operation of the starting air control valve device 20, and the directional interlock device 18. The starting interlock device 21 is in turn controlled by a shift interlock device 22 and by a starting air cut-off valve device 23 by way of a double check valve device 23a. As will be pointed out hereinafter, according to one of the features of the invention, the valve device 23 is arranged to be operable to effect cutting off of the starting air to the engine after same starts to run on fuel.

The shift interlock device 22 is arranged to be controlled by the cam shift cylinder device 10 by way of a lost motion connection in such a manner that in reversing direction of operation of the engine, that is, in shifting the engine cam shaft 2 from one position to another, starting air is supplied to the engine automatically at the time the cam shift cylinder device 10 has completed shift of the cam shaft 2 to condition the engine for operation in a reverse direction, as will be described in detail hereinafter.

A fluid pressure reservoir 25, adapted to be supplied with fluid under pressure from such as a compressor (not shown), is provided to store fluid under pressure for supply to a supply control pipe 26 by way of a reducing valve 27 and to a starting air supply pipe 28 at reservoir pressure.

The speed governor device 5 may, for the purpose of illustration, comprise a head 31 in which a plunger 30 is slidably mounted. Two centrifugal governor fly-ball arms 32 are pivoted on pins 33 in the head 31 and are operatively connected to a collar 34 secured to the plunger 30. The head 31 is operably connected by gears 35, 36 to any suitable rotary part of the engine, such as the crank shaft 1. The plunger 30 is pivotally connected through a link 37 to one end of a lever 38, the opposite end of which lever is operatively connected through a link 39 and pin connections 40, 41 to the fuel control lever 4 on the engine. Intermediate its opposite ends the lever 38 is pivotally connected to a fixed element 42 by means of a pin 43. A speed control spring 44, in the form of a tension spring, is connected to lever 38 in such a manner as will bias the fuel control lever 4 toward its "Full Fuel" position and the plunger 30 downwardly, as viewed in the drawing. Initial tension of the spring 44 will determine the speed setting of the governor device 5 and such tension or setting is arranged to be controlled by the cylinder device 6, as will be described herein subsequently.

In operation of the governor device 5, if the engine is idle and the shaft 1 yet to turn, there will be no force acting through the plunger 30 and lever 38 at one side of pin 43 tending to oppose action of the tension spring 44 on said lever at the other side of said pin, so that the spring 44 will maintain the lever 38 so positioned as will tend to hold the fuel control lever 4 in its "Full Fuel" position, opposite to that in which it is shown in the drawing as held by cut-off cylinder device 17. As will hereinafter become obvious, the speed control cylinder device 6 is operative, when pressure of fluid in the pipe 9 is at atmospheric, as is determined by position of the speed control device 6, as to call for minimum initial tension of the spring 44 acting on lever 38, corresponding to an idling speed setting of the governor device 5, tending to bias the fuel control lever 4 toward its "Full Fuel" position. It should be pointed out, however, that, assuming release of device 17, this minimum tension of spring 44 is sufficiently great as will urge the fuel control shaft 4 to its "Full Fuel" position even though the engine may be turning over on starting air. While the engine is turning over on starting air, the crank shaft 1 will turn, as will the governor head 31 and arms 32, and the arms 32 will cause a force to be exerted upwardly on plunger 30 through the collar 34 tending to effect rocking of lever 38 counter-clockwise about pin 43, but such force of rod 38 at this time, that is, while the engine is being turned over on starting air alone, will not be sufficient to overcome action of spring 44 and effect such rocking of the lever 38, so that the fuel control lever 4 will remain in its "Full Fuel" position if not otherwise moved out of such position by device 17. With the spring 44 thus set for minimum tension corresponding to an idling speed of the engine, when the engine first starts to run on fuel supplied thereto in a maximum amount in accord with the "Full Fuel" position of the fuel control lever 4, the engine speed will tend to increase rapidly over its previous speed when being turned over on starting air alone. As the engine speed increases above starting speed, with the crank shaft 1 and governor head 31 therefore increasing in rotational speed, through centrifugal action a force is caused to be exerted on plunger 30 and thereby lever 38 which will overcome action of

the spring 44 and move the fuel control shaft 4 out of its "Full Fuel" position to an intermediate position in the direction of "Fuel Off" position, tending to reduce the amount of fuel to the engine and thereby its speed, which intermediate position said shaft 4 will assume when a balance is attained between the effect of spring 44 acting on lever 38 at one side of pin 43 and the effect of plunger 30 acting on the other side of said pin on lever 38. Once such balance has thus been established, so long as the tension of spring 44 remains set for minimum initial tension, as above described, the engine will continue to run at idling speed in accord with setting of the fuel control lever 4 in some intermediate position, according to load condition on crank shaft 1. By subsequent increase in tension of spring 44 through operation of speed control cylinder device 6, the speed setting of governor device 5 may be increased and said spring will then cause movement of fuel control lever 4 toward the "Full Fuel" position and thereby increase the speed of the engine until a balance between action of said spring on lever 38 again reaches a balance with the action of plunger 30 on said lever 38. When speed control cylinder device 6 causes a maximum initial tension of the spring 44, the governor device 5 will effect positioning of the fuel control lever 4 in the direction of "Full Fuel" position to increase the speed of the engine to a maximum. In any speed setting of the governor device 5, as determined by the tension of the spring 44, said device 5 will function to maintain such speed of operation of the engine constant. If, while the engine is operating at a certain speed, a change in load on the engine occurs, such as an increase in load, for example, speed of rotation of crank shaft 1 and of the governor head 31 will tend to decrease, thereby tending to reduce the force exerted through centrifugal action by plunger 30 on the lever 38 and allowing spring 44 to move lever 4 in the direction of "Full Fuel" position to supply more fuel to the engine to maintain its speed as determined by the speed setting of the governor device under the increased load. Conversely, for example, the governor device 5 will effect adjustment of the position of the fuel control lever 4 to decrease supply of fuel to the engine for maintaining a speed thereof in accord with the speed setting of said governor device in event that load on the engine should be reduced during its operation.

The speed control cylinder device 6, for sake of illustration, may comprise a casing having a piston 49 slidably disposed therein and subject opposingly to pressure of fluid in a pressure chamber 50 open to the pipe 9 at its one side and to force of a compression spring 51 in a chamber 52 open to atmosphere at its opposite side. The piston 49 is operatively connected to one end of the tension spring 44 through a piston rod 53. Spring 51 urges the piston 49 toward a position indicated in the drawing by a dot and dash line titled "Idling Speed" position in which the initial tension of the spring 44 is at its minimum value calling for idling speed setting of the governor device 5 as before described. By an increase in pressure in chamber 50 up to a maximum value the piston may be caused to assume positions in the direction of chamber 52 toward and to a limit position indicated in the drawing by a dot and dash line titled "Full Speed," and thereby effect increase in the initial tension of the spring 44 up to a maximum value for increasing the speed setting of the governor device 5, as will be appreciated from previous description. By subsequent

controlled reduction in pressure of fluid in the chamber 50, through release of fluid under pressure via the pipe 9, the tension of the spring 44 may be reduced as piston 49 is returned toward 5 and to its "Idling Speed" position. It will be appreciated that any position of piston 49 between "Idling Speed" and "Full Speed" may be effected in accordance with pressure of fluid in chamber 50.

10 It will be seen, therefore, that the speed setting of the governor device 5, hence speed of operation of the engine while running on fuel, will be in accord with the pressure of fluid in the speed control pipe 9 connected to the chamber 50 in the 15 speed control cylinder device 6; a minimum pressure in said chamber such as atmospheric pressure, for example, will correspond to an idling speed setting of the governor device 5 and a maximum pressure of 80 pounds, for example, may 20 correspond to a full speed setting of said governor device.

The resilient link assemblage 7 may comprise a rigid spring cage 55 which is pivotally connected at its one end to one arm of a lever 56 which is attached intermediate its ends to the fuel pressure regulation control shaft 4a. A rod 57 is slidably and guidably mounted within a suitable bore or bores in the cage 55 for pivotal attachment at its one end to a lever 58 which is secured for 25 turning movement with the fuel control shaft 3. A compression spring 59 disposed within a longitudinal chamber 60 formed in the cage 55 encircles the rod 57 and is interposed between a collar 61 attached to the rod 57 and one end of the cage 55. The spring 59 urges the collar 61 to a position seated against a shoulder 63 formed at the opposite end of cage 55 to form a positive connection through which rod 57 attached to lever 30 may move the lever 56 attached to the fuel pressure regulation control shaft 4a in the direction of its "Minimum Fuel Pressure" position. The compression of spring 59 is such as will maintain the collar seated against shoulder 63 during normal control of engine operation by the 35 governor device 5 and therefore will transmit sufficient force between lever 58 and the lever 56 as to allow the fuel control shaft 3 to cause positioning of the fuel pressure regulation control shaft 4a. However, in whatever position out of "Fuel Off" position the fuel control shaft 3 may 40 be in, the resilient link 7 will allow the cylinder device 7a to cause movement of the fuel pressure regulation control shaft 4a to its "Minimum Fuel Pressure" position through actuation of the lever 56. The resilient link assemblage 7 will 45 allow the governor device 5 to move the fuel control shaft 3 to any position, and when the cylinder device 7a is brought into operation, the collar 61 and rod 57 may remain substantially stationary with the lever 58 and fuel control shaft 3 while the cage 55 moves with the lever 58 as shaft 4a is caused by cylinder device 7a to assume its "Minimum Fuel Pressure" position. When the cylinder device 7a is released, the spring 59 will 50 cause return of the cage 55, lever 56, and shaft 4a to its previous position in accord with lever 58 and in which the follower 61 is again seated against the shoulder 63 formed in the cage 55. The cylinder device 7a may comprise a casing 55 having a piston 71 slidably disposed therein and subject to pressure of fluid in a chamber 72 at one side and to the force of a compression spring 73 disposed in an atmospheric chamber 74 at its opposite side. A rod 75 is attached to the piston 71 for movement therewith.

70 The rod 75 extends through the chamber 74

and outwardly through an opening in the end wall of the casing 70 for slidable contact with the opposite arm of the lever 56. In operation of the cylinder device 1a, when fluid under pressure is supplied to the chamber 72, the piston 71 will move in the direction of chamber 74 against action of the spring 73, and in carrying the rod 75 with it, will cause rocking movement of the lever 56 in a clockwise direction as viewed in the drawing, thereby causing the fuel pressure regulation control shaft 4a to be moved to its "Minimum Fuel Pressure" position, if not otherwise therein by virtue of position of lever 58. Upon subsequent release of fluid under pressure from the chamber 72, the spring 73 will cause return of the piston 71 to its original position, in which it is shown in the drawing, thereby allowing the lever 56 and fuel pressure regulation control shaft 4a to again assume its original position in accord with position of lever 58.

The operator's control device 8 may be similar to that shown and described in detail in United States Patent No. 2,413,390 issued to Roy R. Stevens, December 31, 1946, and assigned to the assignee of the present application. For detailed description of the control device 8, therefore, reference may be made to the above patent.

Briefly, the operator's valve device 8 comprises valve means (not shown) for controlling selective establishment and disestablishment of connection between the control supply pipe 26 and the ahead and astern control pipes 11, 12 as well as a start control pipe 76, and for effecting variations in pressure of fluid in the speed control pipe 9. An operator's control lever 77 is provided for controlling operation of the valve means.

The lever 77 extends through a guide slot 78 and has a "Stop" position intermediate the ends of said slot. At one side of "Stop" position, indicated in the drawing by a legend "Ahead," the lever 77 has a "Run and Idle" position which is located substantially midway between "Stop" position and one end of the slot 78 where said lever has a "Full Speed" position. Adjacent to the "Run and Idle" position, the slot 78 opens to a transverse slot 79 to allow for movement of lever 77 to a "Start" position. At the opposite side of "Stop" position, indicated by the legend "Astern," the lever 77 has oppositely arranged corresponding "Run and Idle" and "Full Speed" positions and a similar "Start" position in a slot 80. In "Stop" position of lever 77, the valve means (not shown) controlled by said lever are positioned to open the ahead, astern, speed, and start control pipes 11, 12, 9 and 76, respectively, to atmosphere. In "Run and Idle" position at the "Ahead" side of "Stop" position, the valve means controlled by lever 77 are conditioned to connect the ahead control pipe 11 to the control supply pipe 26 while maintaining the astern control pipe 12, the speed control pipe 9 and the start control pipe 76 vented to atmosphere. By moving lever 77 into slot 79, the start control pipe 76 is also connected to the control supply pipe 26 along with the ahead control pipe 11. In "Run and Idle" position of lever 77 at the opposite or "Astern" side of "Start" position, the astern control pipe 12 is connected to the control supply pipe 26, while the ahead control pipe 11, the speed control pipe 9 and the start control pipe 76 are vented to atmosphere. Upon movement of the lever 77 into the slot 80, the start control pipe 76 is connected to the control supply pipe 26 along with the astern control pipe 12.

When the lever 77 is in either of the "Run and Idle" positions, the speed control pipe 9 is open to atmosphere as above mentioned, for rendering the speed control cylinder device 6 effective to maintain the governor speed setting at idling speed, in which it is shown in the drawing, while upon movement of the operator's control lever 77 to either of the "Full Speed" positions, fluid at a maximum degree of pressure is provided in the speed control pipe 9 for rendering the speed control cylinder device 6 effective to increase the tension of the spring 44 and thereby increase the speed setting of the governor device 5 to a maximum degree to call for operation of the engine at its maximum speed. Any desired speed setting of the governor device may be effected through positioning of cylinder device 6 by suitable adjustment of the operator's control lever 77 between either of the "Run and Idle" positions and the corresponding "Full Speed" position.

While the lever 77 is being positioned within the range between "Run and Idle" and "Full Speed" at the "Ahead" side of "Stop" position, the ahead control pipe 11 will remain connected to the control supply pipe 26, and conversely, while said lever is positioned within the opposite corresponding range at the "Astern" side, the astern control pipe 12 will remain connected to said control supply pipe.

The reversing cylinder device 18 may comprise a casing containing a reversing piston 85 having a piston rod 86 which extends through the casing and has an operative connection with the cam shaft 2 whereby reciprocation of said piston will effect axial movement of said cam shaft. At one side of the piston 85 there is a pressure chamber 87 which is connected to the astern control pipe 12, while at the opposite side of said piston there is a pressure chamber 88 which is connected to the ahead control pipe 11. When fluid under pressure is supplied to the ahead control pipe 11 at a time when chamber 87 is open to atmosphere via pipe 12, the piston 85 will be moved to the position in which it is shown in the drawing for moving the cam shaft 2 to its ahead position to provide for operation of the engine in its ahead direction. Conversely, when fluid under pressure is supplied to the chamber 87 via the astern control pipe 12 while chamber 88 is open to atmosphere via the pipe 11, the piston 85 will be moved to its opposite extreme position to thereby move the cam shaft 2 to its astern position.

The fuel cut-off cylinder device 17, for sake of illustration, may comprise a casing 90 having a piston 91 slidably disposed therein. The piston 91 is subject to pressure of fluid in a chamber 92 at one side and to the opposing force of a compression spring 93 disposed in a chamber 94 at its opposite side. The chamber 94 is constantly open to atmosphere by way of such a port 94' in the casing. A piston rod 95 is attached to the piston 91 for movement therewith. The rod 95 extends through the chamber 94 and end wall of the casing 90 for engagement with the fuel control lever 4. In operation of the cylinder device 17, when fluid under pressure is supplied to the chamber 92, the piston 91 will move in the direction of the chamber 94, carrying the attached rod 95 with it and into engagement with the fuel control shaft 4 which thereby will be caused to assume its "Fuel Off" position, in which it is shown in the drawing. Upon subsequent release of fluid under pressure from the chamber 92, the spring 93 will effect return of the piston 91 to its original position, carrying with it the rod 95.

to a position out of engagement with the fuel control lever 4 which is then again free to assume any position up to and including its "Full Fuel" position.

The directional interlock device 18 may be substantially like that disclosed and described in detail in the United States Patent 2,459,883 issued on January 25, 1949, to Cecil S. Kelly, to which patent reference may be made for a detailed description of said device and in view of which only a brief operational description is included in the present application. Briefly therefore, the directional interlock device 18 is operable in response to supply of fluid under pressure to a pipe 90a to sense the direction of rotation of the engine crank shaft 1, through actuation of a retractable shoe 91a into engagement with said shaft, and to establish communication between one or the other of the ahead or astern control pipes 11, 12 and a pipe 92a according to direction of such rotation, and to maintain such connection when fluid under pressure is subsequently vented from the pipe 90a, with resultant retraction of the shoe 91a away from the shaft 1. If the engine crank shaft 1 is turning in its ahead direction when the shoe 91a is caused to engage said shaft, the directional interlock device 18 will respond to assume what hereinafter will be referred to as its ahead position in which the astern control pipe 12 is connected to the pipe 92a and the latter pipe is disconnected from the ahead control pipe 11. Conversely, if the shaft 1 is rotating in its opposite or astern direction at the time that the shoe 91a is in engagement with said shaft, the directional interlock device 18 will be caused to assume what will hereinafter be referred to as its astern position in which the pipe 92a will be disconnected from the astern control pipe 12 and will be connected to the ahead control pipe 11. If, at the time that shoe 91a is caused to engage the shaft 1, said shaft is not rotating, the interlock device 18 will remain in whichever of its two positions it last assumed during a previous engagement of said shoe with said shaft when it was rotating.

The relay valve devices 19 and 21 as well as the starting air valve device 20 may be substantially alike for sake of illustration. Referring to Fig. 2, each of the devices 19, 20 and 21 may comprise a casing 100 having a diaphragm 101 disposed therein and subject to pressure of fluid in a diaphragm control chamber 102 at its one side and to atmospheric pressure in a chamber 103 at its opposite side, the chamber 103 being open to atmosphere through a port 413. Also formed in the casing are chambers 104, 105 and 106; chamber 104 being separated from chamber 103 by a partition 107 and from chamber 105 by a partition 108. A partition 109 separates chamber 105 from the chamber 106. A valve 110 is disposed in the chamber 104 for controlling communication between the chamber 105 and said chamber 104. The valve 110 may be secured to a fluted stem 111 slidably mounted in a suitable bore extending through the partition 108, a valve seat being formed at the end of the bore opening into the chamber 104 to accommodate the valve 110. A valve 112, similar to the valve 110, is disposed in the chamber 106 for controlling communication between the chamber 105 and said chamber 106. The valve 112 is attached to a fluted stem 113 which is slidably disposed in a suitable bore extending through the partition 109, a valve seat being formed in the end of said bore opening into

the chamber 106 to accommodate the valve 112. Both of the fluted stems 111 and 113 project into and meet in the chamber 105. A bias spring 114 is disposed in the chamber 106 and arranged to urge the valve 112 toward its seat and at the same time, through engagement of stems 111 and 113, to urge the valve 110 away from its seat. The valve 110 is operably connected to the diaphragm 101 by means of a rod or stem 115 extending through a bore in the partition 107. A control spring 116 is provided in chamber 103 to oppose deflection of the diaphragm 101 in the direction of the chamber 103.

In operation of the above device shown in Fig. 15, 2, with the chamber 103 open to atmosphere, upon supply of fluid under pressure to chamber 102 sufficient to overcome action of the control spring 116, the diaphragm 101 will deflect in the direction of the chamber 103, opposing action of the bias spring 114, and will cause seating of the valve 110 and unseating of the valve 112. With valve 110 closed and the valve 112 open, chamber 105 will be closed to the chamber 104 and open to the chamber 106. Upon subsequent reduction 20 in pressure of fluid below a certain value as determined by compression of spring 116, the bias spring 114 and the control spring 116 will return the diaphragm 101 and the valves 110 and 112 to the position in which they are shown in the drawing; the valve 112 being seated and the valve 110 open. The chamber 105, then will be closed to the chamber 106 and open to the chamber 104.

Hereinafter, in describing operation of any of 35 the valve devices 19, 20 or 21 shown in Fig. 1, which are similar to the device shown in detail in Fig. 2, when the valve 110 is unseated and the valve 112 is seated, a communication, indicated symbolically in Fig. 1 of the drawing by a solid line bearing the reference numeral 118, will be established to connect the chamber 105 to the chamber 104. Similarly, when the valve 110 is seated and the valve 112 unseated, a communication, indicated in Fig. 1 of the drawing symbolically by a dash line bearing the reference numeral 119, will be established to connect the chamber 105 to the chamber 106. When one of the communications 118 or 119 is established, the other of said communications is simultaneously 50 disestablished.

Each of the double check valve devices 19a, 19b, and 23a, may be of the usual type having two opposite inlet openings and an outlet opening. Each is operable upon supply of fluid under 55 pressure to either one of its inlet openings to establish connection between that inlet opening and its outlet opening and to close communication between the other inlet opening and said outlet opening, and upon venting of both of its 60 inlet openings to atmosphere to vent its outlet opening.

The starting air cut-off valve device 23 may comprise a casing 305 having a fluid pressure supply chamber 306 connected to the start control pipe 76, a delivery chamber 307 connected to one inlet of the double check valve device 23a by way of a pipe 307', and an exhaust chamber 308 open to atmosphere by way of a port 309. A supply valve 310 is disposed in the supply 65 chamber 306 for controlling communication between said supply chamber and the delivery chamber 307 by way of an opening in a partition 311 separating one chamber from the other. A seat is formed in the partition 311 encircling the opening therein to accommodate the supply

valve 310. A compression spring 312 is also disposed in the supply chamber 308, arranged to urge the supply valve 310 toward a seated position closing the supply chamber from the delivery chamber. The supply valve 310 is connected, by means of a stem extending freely through the opening in partition 311 and the delivery chamber 307, to an exhaust valve seat element 313 slidably mounted within the casing and dividing the delivery chamber 307 from the exhaust chamber 308. An opening 314 in the exhaust valve seat element and in the stem is provided to serve as a communication for connecting the delivery chamber 307 to the exhaust chamber 308 when desired. An exhaust valve 315 is disposed in the exhaust chamber 308 and arranged to cooperate with the seat element 313 to close said chamber 308 to the opening 314. A stem 316, extending outwardly through the casing, is attached to the exhaust valve 315 to provide a medium through which valves 310, 315 may be actuated.

According to a feature of the invention, a retractable cam assemblage 317 is provided for operating the starting air cut-off valve device 23. The cam assemblage 317 comprises a retractable cam 318 carried by a lever element 319 which is secured for turning movement with the fuel control shaft 3. The lever element 319 is provided with a substantially flat surface on which the cam 318 is slidably and pivotally mounted by means of a pin 320. A tension spring 321 is arranged to urge the cam 318 in a counter-clockwise direction about the pin 320, as viewed in the drawing. A stop pin 322 is attached to the lever element 319 for contact with the cam 318 to limit the extent of such counter-clockwise turning movement and define an extended position of said cam, in which position it is shown in the drawing.

In operation of the device 23 by the cam assemblage 317, with the fuel control shaft 3 in its "Fuel Off" position, in which position it is shown in the drawing, the cam 318 will be disposed a distance away from the stem 316 so that the supply valve 310 in device 23 will be closed, with the pipe 307 disconnected from the start control pipe 76 and any fluid under pressure in the former pipe will be free to exhaust itself by unseating the release valve 315.

When the fuel control shaft 3 moves from its "Fuel Off" position to its "Full Fuel" position, as it will be caused to do during operation of the control apparatus to be described hereinafter, the lever element 319 in moving with the shaft 3 will bring the projecting end of the cam 318 into contact with the stem 316, and, due to reluctance of the stem 316 to be displaced inwardly of the casing of the device 23 by virtue of the compression of its spring 312, will cause, first, clockwise pivotal movement of the cam 318 about pin 320 as said cam is passed slidably over the tip of the stem 316, then, when beyond said stem, the spring 321 will return the cam to its extended position seated in contact with the stop pin 322, in which position it will remain as the shaft 3 continues to assume its "Full Fuel" position.

Thus it will be seen that the stem 316 of device 23 will remain in its fully extended position as the fuel control shaft 3 moves from its "Fuel Off" to its "Full Fuel" position, while the cam 318 rides over the projecting end of said stem. The reason for such action will hereinafter become obvious.

Now assume that, with the cam 318 in its ex-

tended position, the fuel shaft 3 is caused to move from its "Full Fuel" position to an "Idling Fuel" position, indicated in the drawing by a dot and dash line so titled, intermediate said "Full Fuel" position and the "Fuel Off" position, as will be the case during a certain operation of the control apparatus to be described hereinafter. Just prior to attaining "Idling Fuel" position, the shaft 3 and lever element 319, will bring a rounded surface portion 325 of the cam 318 into slidable engagement with the projecting end of the stem 316. Such engagement will tend to effect rocking of the cam 318 in a counter-clockwise direction about the pin 320, but such rocking is prevented by the stop pin 322 so that sliding movement of the cam surface portion 325 on stem 316 will effect displacement of the stem 316 inwardly of the casing of device 23 to open the supply valve 310 as a raised portion 326 of the cam is presented to said stem upon attainment of the fuel control shaft 3 to its "Idling Fuel" position. In moving out of "Idling Fuel" position toward either "Fuel Off" or "Full Fuel" positions, the cam 318 will leave the stem 316, which again will be moved to its extended position as the supply valve 310 is closed by the spring 312.

Since "Idling Fuel" position of the fuel control shaft 3 is dependent upon the idling load condition of the engine, and since this may vary in different installations, a set screw 319a is provided to allow for adjustment in angular position of the lever element 319 relative to shaft 3 to assure coincidence between "Idling Fuel" position of said shaft and the position of the cam 318.

The shift interlock valve device 22 may be of a rotary type comprising a rotary valve 200, having two different operating positions, and arranged to be moved to such positions through a lever 201. The lever 201 is operably connected to a link 202 which is slidable on the rod 86 between two spaced apart collars 203 and 204, secured to said rod, thereby providing a lost motion connection with said rod.

When the reversing piston 85 is in its ahead position, in which position it is shown in the drawing, engagement between the link 202 on the rod 86 and the collar 204 attached thereto will position the rotary valve 200 in valve device 2 in what may be called an ahead position, in which position it is shown in the drawing, for connecting the astern control pipe 12 to a pipe 205 which is in turn connected to the other inlet opening of the double check valve device 23a. When the reversing piston 85, and thereby rod 86, is caused to assume its opposite or astern position, the collar 203 will engage the link 202 just before the piston attains such astern position and will actuate the lever 201 to turn the rotary valve 200 to its other position, which position may be called its astern position, to disconnect the astern control pipe 12 from the pipe 205 and to connect the pipe 205 to the ahead control pipe 11. When one of the control pipes 11, 12 is thereby connected to the pipe 205, the other of said control pipes is disconnected from the latter pipe. A cavity 206 is provided in the rotary valve 200 through which the above defined connection may be effected.

In the fuel cut-off cylinder device 17, its chamber 92 is connected to the outlet opening of the double check valve device 19b by way of such as a pipe 400. In the relay valve device 19, its control chamber 102 is connected to the outlet opening of the double check valve device

19a by way of a pipe 401, and its chamber 104 is connected to the control supply pipe 26, its chamber 105 is connected to one inlet opening of the double check valve device 19b by way of a pipe 402, and its chamber 106 is connected to atmosphere by way of such as a pipe 403.

In the double check valve device 19a, one of its inlet openings is connected to the ahead control pipe 11, while the other of its inlet openings is connected to the astern control pipe 12.

In the starting air valve device 20, its control chamber 102 is connected to a branch of the pipe 90a, its chamber 104 is connected to atmosphere by way of such as a pipe 404, its chamber 105 is connected to a pipe 405 which is adapted to be connected to the engine for conveying supply of starting air thereto, and its chamber 106 is connected to the starting air supply pipe 28.

In the relay valve device 21, its control chamber 102 is connected to the outlet opening of the double check valve device 23a by way of a pipe 410, its chamber 104 is connected to the start control pipe 76, its chamber 105 is connected to a branch of the pipe 90a, and its chamber 106 is connected to atmosphere by way of such as a pipe 411.

Operation of apparatus

In operation of the control apparatus embodying the invention, assume that the reservoir 25 is charged with fluid under pressure, as therefore will be the control supply pipe 26 and the starting air supply pipe 28; that the operator's lever 71 of the operator's control device 8 is in its "Stop" position with the ahead, astern speed and start control pipes 11, 12, 9 and 76, respectively, vented to atmosphere; that the engine is stopped after previous operation in its ahead direction, so that the engine cam shaft 2, cam shift cylinder device 10, shift interlock device 22 and directional interlock device 18 each will be in its respective ahead position.

With both the ahead and astern control pipes 11 and 12 vented to atmosphere, the chambers 87 and 88 in the cam shift cylinder device 10, the control chamber 102 in the relay valve device 19, the pipe 205 and the pipe 92a as a consequence also will be so vented to atmosphere, the pipe 92a via directional interlock device 18 and astern pipe 11.

With chambers 87 and 88 in device 10 vented to atmosphere, the cam shift piston 85 will remain static in its "Ahead" position.

With its control chamber vented to atmosphere, the relay valve device 19 will be so positioned that its communication 118 is established, connecting the pipe 402 to the charged control supply pipe 26, so that the chamber 92 in the fuel cut-off cylinder device 17 will be so charged by way of the double check valve device 19b and the pipe 400. The fuel cut-off cylinder device 17 therefore will be in the position in which it is shown in the drawing holding the fuel control lever 4 and shaft 3 in the "Fuel Off" position against opposition of the spring 44 which urges said fuel control lever toward its "Full Fuel" position. With the fuel control shaft 3 thus being held in its "Fuel Off" position, no fuel will be supplied to the engine.

With the fuel control shaft 3 in its "Fuel Off" position through action of the collapsible link 7 and lever 56, the fuel pressure regulating control shaft 3 will be in its "Minimum Fuel Pressure" position, which is incidental at this

time. The cam 318 of assemblage 317 will be in the position in which it is shown in the drawing disposed away from stem 316 with the supply valve 310 in the starting air cut-off valve device 23 closed and pipe 307' vented to atmosphere via the release valve 315 which is free to be unseated by any pressure which might otherwise exist in said pipe 307'.

With both the pipe 307' and the pipe 205 vented to atmosphere, the control chamber 102 of the relay valve device 21 will be so vented by way of the pipe 410 and the double check valve device 23a. The relay valve device 21 therefore will be in its position establishing communication 118 connecting the vented start control pipe 76 to the pipe 90a which thereby also will be vented at this time.

Now assume that the operator desires to start the engine to operate in the same or ahead direction in which it operated last. He will then move the operator's control lever 71 from "Stop" position in the slot 78 to the "Ahead" "Start" position in the slot 79, thereby effecting supply of fluid under pressure to the ahead control pipe 11 and start control pipe 76, while the astern and speed control pipes 12 and 9 are maintained vented to atmosphere.

Since the engine cam shaft 2 and cam shift piston 85 are already in their ahead positions at this time, fluid under pressure supplied via the ahead control pipe 11, to the chamber 88 in device 10 will not affect said piston which will remain static.

Since the directional interlock device 18 is in its ahead position, the pipe 92a will be connected to the vented astern control pipe 12, so that when fluid under pressure from the ahead control pipe 11, supplied to the control chamber of the relay valve device 19 by way of the double check valve device 19a causes said relay valve device 19 to establish its communication 119, fluid under pressure from the chamber 92 in the fuel cut-off cylinder device 17 will flow to atmosphere by way of the double check valve device 19b, pipe 402, said communication, and the pipe 403. The piston 91 in the fuel cut-off cylinder device will then be moved by spring 93 to a rest position in which the rod 95 is disposed away from the fuel control lever 4, which will be caused to assume its "Full Fuel" position by action of the spring 44. The fuel control shaft 3 therefore is likewise caused to assume its "Full Fuel" position for allowing fuel to be supplied to the engine, and in assuming such position, through the link assemblage 7 and lever 56, the fuel pressure regulating control shaft 4a will be caused to assume its "Maximum Fuel Pressure" position to call for a maximum pressure of such fuel. The cam 318, as aforescribed, will be carried past the stem 60 316 of the device 23 as the shaft 3 assumes its "Full Fuel" position, while the device 23 remains positioned disconnecting the start control pipe 76 from the pipe 307'.

Substantially at the same time that the above occurs, fluid under pressure supplied to the start control pipe 76 will flow by way of the communication 118 in the relay valve device 21 and the pipe 90a to the control chamber of the starting air control valve device 20 and to the chamber 72 in the cylinder device 7a.

Fluid under pressure thus supplied to the control chamber of the starting air control valve device 20 will cause said device to establish its communication 119 connecting the pipe 405 to the pipe 28, whereupon fluid at reservoir pressure will

flow via these pipes to the engine, causing same to turn over in its ahead direction in accord with the "Ahead" position of the engine cam shaft 2.

At the same time, fluid under pressure supplied as aforementioned to the chamber 72 in the cylinder device 7a will cause said cylinder device to rock the fuel pressure regulating control shaft 4a from its "Maximum Fuel Pressure" position to its "Minimum Fuel Pressure" position, while the fuel control shaft 3 is allowed to remain in its "Full Fuel" position by virtue of the link assemblage 7, as aforescribed. By so moving the fuel pressure regulating control shaft 4a at this time, that is at a time when both starting air and fuel are being supplied to the engine to start same, the supply pressure of such fuel is kept at a minimum so that the amount of such fuel flowing into the engine will not be so great as though such pressure were a maximum value and shock to the engine due to ignition of the fuel will be precluded.

When such fuel supplied along with the starting air ignites, the engine takes off at increasing speed above that at which it was being turned over by the starting air, and the speed governor device 5 will respond to move the fuel control shaft 3 via the lever 4 from its "Full Fuel" position to its "Idling Fuel" position to so limit the amount of fuel to the engine as to maintain its speed in accord with the "Idling Speed" setting of the governor device at this time.

In thus being moved from its "Full Fuel" position to its "Idling Fuel" position, the fuel control shaft 3 will carry with it the retractable cam assemblage 317 and will cause, through actuation of the stem 316, seating of the release valve 315 and unseating of the supply valve 310 in the starting air cut-off valve device 23, in manner as aforescribed. Fluid under pressure from the charged start control pipe 76 will then flow via the unseated valve 310 in device 23, the pipe 307, the double check valve 23a and the pipe 410 into the control chamber of the relay valve device 21. The relay valve device 21 will then respond to disestablish its communication 118 which connects the start control pipe 76 to the pipe 90a and to establish its communication 119 which connects the pipe 90a to the pipe 411, thence to atmosphere. Fluid under pressure will then release via the pipe 90a from the control chamber in the relay valve device 20 and from the chamber 72 in the cylinder device 7a.

In response to release of fluid under pressure from its control chamber, the starting air control valve device 20 will respond to disestablish its communication 119 which connects the pipe 405 to the supply pipe 28 and to establish its communication 118 which connects said pipe 405 to the pipe 404 and thereby to atmosphere. Supply of starting air to the engine thus is terminated automatically without necessitating movement of the lever 71 out of "Start" position by the operator of the apparatus.

At the same time, release of fluid under pressure from the chamber 72 in the cylinder device 7a will allow the spring 73 to move the piston 71 and rod 75 to a rest position out of engagement with the lever 56, so that the link assemblage 7 will contract to bring the position of the fuel pressure regulating control shaft 4a into accord with the "Idling Fuel" position of the fuel control shaft 3 for varying the pressure of fuel supplied to the engine substantially in direct proportion to the opening of the fuel control valve as determined by position of the fuel control shaft.

The operator may then move the operator's lever 77 from its "Start" position in the slot 79 into the slot 78 to its "Ahead" "Run and Idle" position, thereby effecting venting of the start control pipe 76 along with the speed and astern control pipes 9 and 12 which will remain vented at this time while the ahead control pipe 11 remains charged.

With the start control pipe 76 thus vented to 10 atmosphere, fluid under pressure will release from the control chamber of the relay valve device 21 by way of the pipe 410, the double check valve 23a, the pipe 307, the unseated supply valve 310 in the valve device 23, and said start 15 control pipe to atmosphere. The relay valve device 21 will then respond to disestablish its communication 119 which connects the pipe 90a to the pipe 411 to atmosphere and to establish the communication 118 which connects said pipe 90a 20 to the now vented start control pipe 76, so that the pressure status of the pipe 90a is not changed at this time.

With the engine thus running at its idling 25 speed on fuel supplied thereto, if the operator 28 desires to adjust the speed of the engine, he may so do by adjustment of position of the lever 77 in slot 78 to and between "Ahead" "Run and Idle" and "Ahead" "Full Speed" according to the speed desired. As will be appreciated from previous description, such change in speed is effected 30 through variation in pressure of fluid in the speed control pipe 9 as reflected in the speed control cylinder device 6 for varying the speed setting of the governor device 5 by resultant differences in 35 the tension of the spring 44.

It should be pointed out at this time, that the automatic cut-off of starting air as effected through movement of the fuel control shaft 3 from its "Full Fuel" position to its "Idling Fuel" 40 position is not dependent upon the "Idling Fuel" position remaining fixed, as this position may shift somewhat between "Full Fuel" and "Fuel Off" with slight changes in the no load conditions imposed on the engine at time of starting; the width of the surface portion 326 on the cam 45 318 is such as will cause displacement of the stem 316 through a relatively wide range of fuel control shaft positions.

When the operator desires to stop the engine 50 while it is running in its ahead direction, he may move the operator's lever 77 from its position in slot 78 at the "Ahead" side of "Stop" position to the "Stop" position, thereby effecting venting of the speed and ahead control pipes 9 and 11 55 to atmosphere along with the astern and start control pipes 12 and 76 which remain so vented.

In response to venting of the speed control pipe 9 to atmosphere, the piston 49 in the speed control cylinder device 6 will return to its "Idling Speed" position, adjusting the initial tension of the spring 44 to call for an "Idling Speed" setting of the governor device 5.

In response to venting of the ahead control pipe 11 along with the astern control 12, fluid 60 under pressure in the control chamber of the relay valve device 19 will flow to atmosphere by way of the pipe 401 and the double check valve device 19a. The relay valve device 19 will then respond to disestablish its communication 119 65 which vents the pipe 402 to atmosphere and to establish its communication 118 which connects said pipe 402 to the supply pipe 26. Fluid under pressure from the pipe 26 will then flow by way of the device 19, the pipe 402, the double check 70 valve device 19b, and the pipe 400 to the cham- 75

ber 92 in the fuel cut-off cylinder device 17, which device will then respond to move the fuel control shaft 3 to its "Fuel Off" position to terminate supply of fuel to the engine for stopping same.

In moving to its "Fuel Off" position, the fuel control shaft 3 will effect, through the link 7, movement of the fuel pressure regulating control shaft 4a to its "Minimum Fuel Pressure" position, and movement of the cam assemblage 317 to the position in which it is shown in the drawing, with the cam 318 disposed away from the stem 316 of device 23 which will assume its fully extended position.

All parts of the apparatus will thus assume the respective positions in which they are shown in the drawing and which they were described to have assumed previously herein after operation in the ahead direction.

With the engine stopped after operation in its ahead direction, assume that it is desired to start the engine operating in its opposite or astern direction. The operator will then move the operator's lever 77 out of "Stop" position in the slot 78 to "Astern" "Start" position in the slot 80, thereby causing fluid under pressure to be supplied to the astern and start control pipes 12 and 76, while the ahead and speed control pipes 11 and 9 are maintained vented to atmosphere.

Fluid under pressure thus supplied to the astern control pipe 12 will flow by way of passage 206 in the shift interlock device 22, the pipe 205, the double check valve device 23a, and the pipe 410 into the control chamber in the relay valve device 21 which will respond to disestablish its communication 118 and to establish its communication 119 for disconnecting the pipe 90a from the start control pipe 76 and for venting the former pipe to atmosphere to prevent supply of starting air to the engine before the cam shaft 2 is shifted to its astern position to condition the engine for operation in that direction, as will be appreciated from subsequent description.

Substantially at the same time, fluid under pressure supplied as aforementioned to the astern control pipe 12 will flow by way of the directional interlock device 18, which is in its ahead position, the pipe 92a, the double check valve device 19b, and the pipe 400 to the chamber 92 in the fuel cut-off cylinder device 17 to maintain the fuel supply cut-off to the engine as the pipe 402 is vented to atmosphere by establishment of the communication 119 in the relay valve device 19 in response to supply of fluid under pressure to its control chamber from the charged astern control pipe 12 by way of the double check valve 19a and the pipe 401, as will be appreciated from previous description.

While the above is occurring, fluid under pressure from the astern control pipe 12 also will flow into the chamber 87 in the cam shift cylinder device 10, the chamber 88 of which is vented at this time by way of the ahead control pipe 11, causing the cam shift piston 85, and thereby the engine cam shaft 2, to assume its "Astern" position, opposite to that in which it is shown in the drawing, to condition the engine for operation in its astern direction.

Substantially upon attainment of the cam shift piston 85 to its "Astern" position, the collar 203 on the attached rod 86 will engage the link 202 and cause shifting of the lever 201, hence valve 200, to its "Astern" position, thereby disconnecting the pipe 205 from the charged astern control pipe 12 and connecting said pipe 205 to the now

vented ahead control pipe 11 by way of the passage 206 in said valve 200.

When the pipe 205 thus is vented to atmosphere at this time, since the pipe 307' also is so vented via the device 23, fluid under pressure from the control chamber in the relay valve device 21 will release to atmosphere by way of the pipe 410, double check valve device 23a and the pipe 205, with the result that said relay valve device will respond to disestablish its communication 119 which vents the pipe 90a to atmosphere and to establish its communication 118, thereby connecting the pipe 90a to the charged start control pipe 76, for causing starting air to be supplied to the engine now that the engine cam shaft 2 is properly set for astern operation.

Fluid under pressure thus supplied to the pipe 90a will flow to the control chamber in the starting air control valve device 20, into the chamber 72 in the cylinder device 7a, and to the direction interlock device 18 to cause engagement of its shoe 91a with the shaft 1. The directional interlock device will, however, remain in its ahead position until the crank shaft 1, which is now stopped, turns in its astern direction, as will be understood from previous description.

In response to fluid under pressure thus supplied to its control chamber, the starting air control valve device 20 will respond to disestablish its communication 118 which connects the pipe 90a to atmosphere and to establish its communication 119, thereby connecting the pipe 405 to the supply pipe 28 to allow fluid under pressure from the latter pipe to flow via the former pipe to the engine for causing same to turn over in its astern direction.

At the same time, substantially, that the above is occurring, fluid under pressure supplied via the pipe 90a to the chamber 72 in the cylinder device 7a will cause the piston 71 and attached rod 75 to engage the lever 56 and hold the fuel pressure regulating control shaft 4a in its "Minimum Fuel Pressure" position upon subsequent movement of the fuel control shaft 3 to its "Full Fuel" position, as will be subsequently described, to prevent excessive supply of fuel to the engine at time of starting. It should be appreciated, that the improved control apparatus forming the subject matter of the present disclosure, including the retractile cam assemblage 317, may be employed without the use of the cylinder device 7a on engines which do not provide means for controlling the fuel pressure in such a manner as will call for a maximum fuel pressure with the throttle or fuel control valve wide open at "Full Fuel."

Upon supply of starting air to the engine as aforementioned, the engine will turn over in its astern direction at some speed less than that at which it idles when running on fuel. Upon initial turning movement of the engine crank shaft 1 in its astern direction, the directional interlock device 18 will be caused to assume its astern position in which the pipe 92a is disconnected from the now charged astern control pipe 12 and becomes connected to the now vented ahead control pipe 11. Since at this time the pipe 402 is vented to atmosphere by way of the communication 119 in the relay valve device 19, fluid under pressure will release from the chamber 92 in the fuel cut-off cylinder device 17 by way of the pipe 400, the double check valve 19b and the pipe 92a, thereby allowing the spring 93 in device 17 to move the piston 91 to the position in which the attached rod 95 is out of engagement with the

fuel control lever 4, allowing the spring 44 to move the fuel control lever and thereby the fuel control shaft 3 to its "Full Fuel" position. The fuel control valve device (not shown) operated through the fuel control shaft 3 will then be wide open to allow flow of fuel to the engine along with the starting air. The amount of fuel flowing to the engine through the wide open fuel control valve device will be limited to a desirable amount by the pressure of such fuel which will be at a minimum at this time due to the fuel pressure regulating shaft 4a being held by cylinder device 7a in its "Minimum Fuel Pressure" position. The link assemblage 7 allows the shaft 4a to be held in the above mentioned position while the fuel control shaft 3 is caused to assume its "Full Fuel" position, as will be appreciated from previous description.

When the fuel cut-off cylinder device 17 is released, as above described, and the fuel control shaft 3 moves from its "Fuel Off" position to its "Full Fuel" position, the cam assemblage 317, in moving with said shaft 3 will carry the retractable cam 318 with it past the stem 316 of device 23 to a position on the side opposite to that in which it is shown in the drawing. The stem 316 of the device 23 will remain in its fully extended position during such movement of the cam assemblage 317, as will be appreciated from previous description, so that the pipe 307 will remain vented to the atmosphere via said device.

When the fuel thus supplied to the engine along with the starting air fires, it will cause running of the engine at an increasing speed above that at which it was being turned over on starting air as described. In response to such an increase in speed, the speed governor device 5 will effect movement of the fuel control shaft 3 to its "Idling Fuel" position to so limit the amount of fuel supplied to the engine as to maintain its speed in accord with the speed setting of the governor device as determined by the initial tension of the spring 44 under the influence of the speed control cylinder device 6; the pressure of fluid in the speed control pipe 9 being at atmospheric pressure at this time.

During such movement of the fuel control shaft 3 from "Full Fuel" to "Idling Fuel" position, the cam 318 of the cam assemblage 317 will be carried by the lever element 319 into displacing engagement with the stem 316, which is thereby moved inwardly of the casing of the device 23, as will be appreciated from previous description, unseating the valve 310 while holding valve 315 closed. Fluid under pressure from the start control pipe 76 will then flow by way of the unseated valve 319 in the device 23, the pipe 307, the double check valve 23a and the pipe 410 into the control chamber in the relay valve device 21, which then will respond to disestablish its communication 118 which connects the pipe 90a to the start control pipe 76 and to establish its communication 119 which vents said pipe 90a to the atmosphere. By way of the pipe 90a, fluid under pressure will then release from the control chamber of the starting air control valve device 20 to cause termination of supply of starting air to the engine through disestablishment of its communication 119 and establishment of its communication 118, from the chamber 72 in the cylinder device 7a to effect retraction of the stem 75 away from the lever 56 to allow the fuel pressure regulating control shaft 4a to assume its position in accord with position of the fuel control shaft 3, and from the directional interlock

device 18, now in its astern position, to effect retraction of its shoe 91a away from the engine crank shaft 1.

It should be pointed out that when the fuel pressure regulating control shaft 4a is released by retraction of stem 75, the shaft 4a will move from its "Minimum Fuel Pressure" position to a position intermediate the last named position and its "Maximum Fuel Pressure" position, thus causing an increase in the pressure of fuel supplied via the fuel control valve device to the engine, the effect of which will be to momentarily increase the amount of fuel to the engine for the particular setting of said fuel control valve at the time. The speed governor device 5, however, will respond to prevent persistence of such additional amount of fuel above that required to maintain idling speed of the engine by moving the fuel control shaft 3 out of "Idling Fuel" position to a position toward "Fuel Off" position to maintain a constant idling speed. The cam assemblage 317 thus will move with the fuel control shaft 3 during such adjustment of its position, and the cam 318 will slide on the stem 316 of the device 23, but due to the width of said cam, same will not leave said stem at this time, so that the pipe 307 will remain connected to the yet charged start control pipe 76.

With the engine thus running at its idling speed on fuel and with the starting air having been cut off automatically, the operator will then move the operator's control lever 77 out of its "Astern" "Start" position in the slot 80 to its opposite "Astern" "Run and Idle" position in the slot 78, thereby effecting venting of the start control pipe 76 to atmosphere along with the ahead and speed control pipes 11 and 9, which will remain so vented, while maintaining the astern control pipe 12 charged with fluid under pressure.

The operator may then control the speed of the engine operating in its astern direction through adjustment in position of the operator's lever 77 in the slot 78 to and between "Astern" "Run and Idle" and "Astern" "Full Speed" positions. Such adjustment in position of the lever 77 will effect the necessary variation in pressure of fluid in the speed control pipe 9, and through resultant variation in the speed setting of the governor device 5 cause adjustment in position of the fuel control shaft 3 to regulate supply of fuel to the engine to maintain such speed in accord with such governor speed setting. During such speed adjustment, in moving with the fuel control shaft 3, the cam assemblage 317 will carry the cam 318 past the stem 316, allowing same to move to its fully extended position as the valve 310 in the device 23 is closed by the spring 312. Fluid under pressure will then release from the control chamber in the device 21 to atmosphere by way of the pipe 410, double check valve 23a, the pipe 307 and the valve 315 in device 23. The relay valve device 21 will then respond to disestablish its communication 119 and to establish the communication 118 thus connecting the pipe 90a to the now vented start control pipe 76, so that at this time the pressure status of the pipe 90a will not change, the starting air control valve device 20, the cylinder device 7a, and the directional interlock device 18 remaining in their respective positions as aforescribed.

When the operator desires to stop the engine thus running in its astern direction, he may move the operator's control lever 77 from its position at the "Astern" side of "Stop" position to said "Stop" position, thereby effecting venting of the speed control pipe 9 in passing through "Run and

"Idle" position and venting of the astern control pipe 12 upon attainment of said "Stop" position, while maintaining the ahead, speed and start control pipes 11, 9 and 76 also so vented in the latter position.

Upon venting of the speed control pipe 9 to atmosphere, fluid under pressure will release from the chamber 50 in the speed control cylinder device 6 by way of said pipe. The spring 51 will then move the piston 49 to its "Idling Speed" position in which the attached rod 53 is so disposed as to cause a minimum initial tension on the spring 44, defining an "Idling Speed" setting of the governor device 5, which will respond to adjust position of fuel control lever 3 accordingly.

When the astern control pipe 12 is vented to atmosphere as aforementioned along with the ahead control pipe 11 in "Stop" position of the operator's lever 77, fluid under pressure will release from the control chamber in the relay valve device 19 by way of the double check valve 19a, to which release said valve device will respond to disestablish its communication 119 which connects the pipe 402 to atmosphere and to establish its communication 118 to connect said pipe 402 to the fluid pressure supply pipe 26. Fluid under pressure will then flow from the supply pipe 26, through the communication 118 in the relay valve device 19, through the pipe 402, the double check valve 19b and the pipe 400, into the chamber 92 in the fuel cut-off cylinder device 17, which thereby will be caused to assume the position in which it is shown in the drawing, holding the fuel control shaft 3 in its "Fuel Off" position through engagement of the rod 95 with the fuel control lever 4. In being caused to assume its "Fuel Off" position, the shaft 3 will cause termination of supply of fuel to the engine for stopping same.

At the same time, in being caused to assume its "Fuel Off" position, the fuel control shaft 3 will cause movement of the fuel pressure regulating control shaft 4a to its "Minimum Fuel Pressure" position through the medium of the link assemblage 7 and the lever 56, while the cam assemblage 317 will assume the position in which it is shown in the drawing, with its cam 318 out of engagement with the stem 316 of the device 23.

The valve 318 in the device 23 will be held in its closed position by the spring 312, while any pressure of fluid in the pipe 307' is free to reduce to atmosphere by unseating the valve 315 in absence of opposition from any force being exerted on the stem 316. The pipe 205, also being vented to atmosphere, by way of the shift interlock device 22 in its astern position opposite to that in which it is shown in the drawing and the ahead control pipe 11, the control chamber in the relay valve device 21 will be so vented by way of the double check valve 23a.

The relay valve device 21 will therefore remain in its position establishing its communication 118 which connects the pipe 90a to the now vented start control pipe 76.

The pipe 90a thus will be vented to the atmosphere at this time by way of the start control pipe 76, so that the control chamber in the starting air control valve device 20 will be devoid of fluid under pressure and the pipe 405 therefore vented to atmosphere via communication 118 in said device 20, the chamber 72 in the cylinder device 1a will be devoid of fluid under pressure, so that said device 1a will remain in the position in which it is shown in the drawing with its stem 75 disposed away from the lever 56, and the shoe 91a in the directional interlock

device 18 will be disposed in a position out of engagement with the engine crank shaft 1.

It will be noted that all parts of the apparatus, in response to movement of the operator's lever 77 to "Stop" position while the engine is running in its astern direction, will assume the positions in which they are shown in the drawing or in which they were aforescribed to have assumed in "Stop" position of lever 77 subsequent to operation of the engine in its ahead direction with the exception of the cam shift cylinder device 10, the engine cam shaft 2, the cam shift interlock device 22, and the directional interlock device 18, which all remain in their respective astern positions as previously defined.

Now assume that the engine is operating in its ahead direction with the operator's lever 77 in a position in the slot 78 in or intermediate "Ahead" "Full Speed" and "Ahead" "Run and Idle" positions and that it is desired to effect a so called snap reversal in the direction of operation of the engine, that is, from ahead to astern. The parts of the control apparatus will be positioned as previously described under these assumed conditions.

The operator will then move the operator's lever 77 from its position in slot 78 at the "Ahead" side of "Stop" position to its "Start" position in the slot 80 at the "A stern" side of "Stop" position, thereby effecting venting of the speed control pipe 9 in passing through "Ahead" "Run and Idle" position, venting of the ahead control pipe 11 and supply of fluid under pressure to the astern control pipe 12 in passing through "Stop" position, and upon attainment of "A stern" "Start" position, effecting supply of fluid under pressure also to the start control pipe 76.

Upon venting of the speed control pipe 9, the piston 49 in the speed control cylinder device 6 will assume its "Idling Speed" position, to which the speed governor device 5 will respond to move the fuel control shaft 3 and pressure regulating control shaft 4a to a position to call for operation of the engine at idling speed in accord with the speed setting of the governor device.

Venting of the ahead control pipe 11 and supply of fluid under pressure to the astern control pipe 12 in rapid succession will maintain the control chamber in the relay valve device 19 charged with fluid under pressure by way of the double check valve 19a, so that the communication 119 in said relay valve device will remain established, maintaining the pipe 402 vented to atmosphere.

Fluid under pressure supplied to the astern control pipe 12, however, will flow by way of the directional interlock device 18 which is in its ahead position at this time, into the pipe 92a, and through the double check valve 19b and the pipe 400 to the chamber 92 in the fuel cut-off cylinder device 17, which will respond to move the fuel control shaft 3 to its "Fuel Off" position through engagement of the stem 95 with the fuel control lever 4, to cause termination of supply of fuel to the engine for terminating its operation in the ahead direction. At this time, the fuel pressure regulating shaft 4a will be caused to assume its "Minimum Fuel Pressure" position and the cam assemblage 317 will be caused to assume the position in which it is shown in the drawing with its cam 318 disposed away from the stem 316, so that the pipe 307' will remain vented to atmosphere.

At the same time, fluid under pressure supplied to the astern control pipe 12, upon shift

of the operator's lever 17 will flow by way of the shift interlock device 22 into the pipe 205 and thence through the double check valve 23a and the pipe 410 to the control chamber in the relay valve device 21 to disconnect the pipe 90a from the start control pipe 76 until the engine cam shaft 2 is shifted. The pipe 90a in being vented to atmosphere by way of the communication 119 in relay valve device 21 will prevent operation of the starting air control valve device 20, the cylinder device 7a and the directional interlock device 18 at this time.

Also at the same time and while the above is occurring, fluid under pressure supplied to the astern control pipe 12 will flow into the chamber 87 in the cam shift cylinder device 10, and since the chamber 88 in device 10 is vented to atmosphere by way of the ahead control pipe 11 at this time, this fluid under pressure in chamber 87 will cause movement of the cam shift piston 86, and through rod 86, also the engine cam shaft 2, to its "A stern" position to condition the engine for operation in the corresponding direction.

Substantially upon attainment of the engine cam shaft 2 to its "A stern" position, the collar 203 on the rod 86 will engage the link 202, and acting through the lever 201, will cause the rotary valve in the shift interlock device 22 to assume its "A stern" position in which the pipe 205 is disconnected from the now charged astern control pipe and becomes connected to the now vented ahead control pipe 11. Fluid under pressure will then release from the control chamber in the relay valve device 21 by way of the pipe 410, the double check valve 23a, and the pipe 205, since the pipe 307 is also vented at this time, to allow starting air to be supplied to the engine now that the engine reversing mechanism is properly set for astern operation of the engine.

The relay valve device 21 will respond to such release of fluid under pressure from its control chamber to disestablish its communication 119 which connects the pipe 90a to atmosphere and to establish its communication 118 which connects said pipe 90a to the now charged start control pipe 76. Fluid under pressure from the start control pipe 76 will then flow through communication 118 in the relay valve device 21 and through the pipe 90a to the control chamber in the starting air control valve device 20, to the chamber 72 in the cylinder device 7a, and to the directional interlock device 18.

In response to supply of fluid under pressure to its control chamber as above, the starting air control valve device 20 will disestablish its communication 118 which connects the pipe 405 to atmosphere and will establish its communication 119 which connects said pipe 405 to the starting air supply pipe 28. Starting air from the pipe 28 will then flow via the pipe 405 to the engine, and if the engine is yet turning over in its ahead direction, such starting air supplied at this time will act to decelerate the engine turning over in its ahead direction, and/or, when the engine is stopped, will turn same over in its new or astern direction.

Fluid under pressure supplied to the chamber 72 in the cylinder device 7a will cause the stem 35 to be brought into engagement with the lever 46 to hold the fuel pressure regulating control shaft 4a in its "Minimum Fuel Pressure" position when the fuel control shaft 3 subsequently is moved to its "Full Fuel" position to limit the

amount of fuel supplied to the engine in starting, as will be appreciated from previous description.

In response to supply of fluid under pressure to the pipe 90a, the shoe 91a of the directional interlock device 18 will be caused to assume its extended position in engagement with the engine crank shaft 1 to sense the direction of rotation of same. Upon initial turning movement of the engine crank shaft 1 in its new or astern direction, the directional interlock device will shift from its ahead to its astern position, disconnecting the pipe 92a from the charged astern control pipe 12 and connecting said pipe 92a to the now vented ahead control pipe 11.

Since at this time the pipe 402 is vented to atmosphere by way of communication 119 in the relay valve device 49, when the pipe 92a is connected by way of the directional interlock device 18 to the now vented ahead control pipe 11 as above, fluid under pressure will release from the chamber 92 in the fuel cut-off cylinder device 17 by way of the pipe 400, the double check valve 18b and said pipe 92a. In response to release of fluid under pressure from its chamber 92, the fuel cut-off cylinder device 17 will retract its stem 75 away from the fuel control lever 4, thereby allowing the spring 44 of the governor device 5 to move the fuel control shaft 3 from its "Fuel Off" position to its "Full Fuel" position, which it will then so do, for allowing fuel to be supplied to the engine along with the starting air which is turning same over in its astern direction. At this time the cylinder device 1a will hold the fuel pressure regulating control shaft 4a in its "Minimum Fuel Pressure" position to prevent excessive supply of fuel to the engine with the fuel control shaft 3 in its "Full Fuel" position, as will be appreciated from previous description.

As the fuel control shaft 3 is moved from its "Fuel Off" position to its "Full Fuel" position as above, the cam assemblage 317 will move along with it, carrying the cam 318 past the stem 316 to a position on the side of said stem opposite to that in which it is shown in the drawing; the cam 318 pivoting on pin 328 in a clockwise direction, as shown in the drawing, relative to lever element 319 in passing over the stem 316 which remains in its fully extended position while such is occurring, as will be appreciated from previous description. The pipe 307 therefore will remain vented to atmosphere by way of the device 23 at this time.

When the fuel being supplied to the engine along with the starting air fires, the engine will start to run at increasing speed above that which it was being turned over on starting air alone. The speed governor device 5 will respond to such increase in engine speed to effect movement of the fuel control shaft 3 from its "Full Fuel" position to its "Idling Fuel" position to maintain the engine running at its idling speed in accord with the speed setting of the governor device.

During such movement of the fuel control shaft 3 from its "Full Fuel" position to its "Idling Fuel" position, the cam assemblage 317 in moving with said shaft 3 will bring the cam 318 into displacing engagement with the stem 316 of the device 23, as will be appreciated from previous description, unseating the valve 310 and thereby allowing fluid under pressure from the start control pipe 48 to flow into and through the pipe 307, the double check valve 23a and the pipe

410 to the control chamber in the relay valve device 21.

In response to fluid under pressure thus supplied to its control chamber, the relay valve device 21 will disestablish its communication 118 which connects the pipe 90a to the now charged start control pipe 76 and will establish its communication 119 which connects said pipe 90a to the atmosphere, thereby allowing fluid under pressure to release from the control chamber in the starting air control valve device 20 to terminate supply of starting air to the engine which is now running on fuel in its astern direction, from the chamber 72 in the cylinder device 7a to allow the fuel pressure regulating control shaft 4a to assume its position in accord with dictates of the fuel control shaft 3, as will be appreciated from the previous description, and from the directional interlock device 18 to allow for retraction of its shoe 91a; termination of supply of starting air to the engine being effected through disestablishment and establishment of communications 119 and 118, respectively, in the relay valve device 20, and freedom of the shaft 4a from the cylinder device 7a being effected through retraction of the stem 75 away from the lever 56.

Again, as aforescribed, upon releasing the fuel pressure regulating control shaft 4a, its resultant shift in position may affect the position of the fuel control shaft 3 through the speed governor device 5, but such shift in position of the fuel control shaft will not be sufficiently great as to cause the cam 318 of assemblage 317 to leave the stem 316 of the device 23. It will be seen that the stem 316, therefore, will remain in its displaced position at this time, with the valve 310 in device 23 remaining open and the pipe 307 consequently remaining connected to the yet charged start control pipe 76. It will be seen, too, that the relay valve device 21 will remain positioned to condition the starting air control valve device 20 for holding the starting air cut-off from the engine at this time.

With the engine thus running on fuel at its idling speed in its astern direction, the operator will then move the operator's handle 77 out of "Astern" "Start" position in the slot 80 to its "Astern" "Run and Idle" position in the slot 78, thereby effecting venting of the start control pipe 76 to atmosphere along with the speed control pipe 9 and the ahead control pipe 11 which will remain so vented at this time, while maintaining the astern control pipe 12 charged with fluid under pressure.

In response to venting of the start control pipe 76 to atmosphere, fluid under pressure from the control chamber in the relay valve device 21 will release by way of the pipe 410, double check valve 23a, pipe 307, the unseated valve 310 in the device 23, and said start control pipe 76. The relay valve device 21 will then respond to disestablish its communication 119 which connects the pipe 90a to atmosphere via pipe 411 and to establish its communication 118 which connects the pipe 90a to the now vented start control pipe 76, so that the pressure status of said pipe 90a will remain uncharged at this time, with the starting air control valve device 20, the cylinder device 7a and the directional interlock device 18 remaining positioned as before, closing off starting air to the engine, allowing freedom of movement of the fuel pressure regulating control shaft

4a and maintenance of retraction of the shoe 91a in the directional interlock device 18.

In the manner as aforescribed, the operator may then regulate the speed of operation of the engine in its astern direction through variations in pressure of fluid in the speed control pipe 9 as effected through adjustment in position of the operator's control lever 77 in slot 78 to and between "Astern" "Run and Idle" and "Astern" "Full Speed" positions according to the speed desired.

When the operator desires to stop the engine thus operating in its astern direction, he may then move the operator lever 77 from whatever position it may be in at the "Astern" side of "Stop" position in the slot 78 to "Stop" position. The parts of the apparatus will then assume their respective positions as previously described in regard to stopping the engine from operation astern.

It will be appreciated that a "snap reversal" of the engine to its ahead direction of operation might be effected while same is operating in its astern direction in a manner similar to the preceding description, by moving the operator's control lever 77 from its position in slot 78 on the "Astern" side of "Stop" position to the "Ahead" "Start" position in slot 79. For sake of brevity, description of "snap reversal" in direction of operation of the engine opposite to that described herein is not repeated, it being understood from the former description that such is possible.

Summary

It will now be seen that I have provided a relatively simple improved control apparatus for controlling the starting, running, stopping, reversing, etc. of a reversible diesel engine.

According to one of the features of the invention, it will be seen that I have provided improved means for effecting cut-off of supply of starting air to the engine automatically upon running of the engine on fuel. Such improved means is operative to effect such cut-off when the engine fuel control shaft is moved by the engine speed governor from its "Full Fuel" position to an "Idling Fuel" position intermediate said "Full Fuel" position and its "Fuel Off" position. Since the "Idling Fuel" position may vary somewhat under different no-load conditions on various engines and installations, the improved means is adapted for operation over a range of "Idling Fuel" positions without requiring adjustment.

According to another of the features of the invention, it will be seen that I have provided a cylinder device which is operative in conjunction with a resilient link assemblage 7 to actuate a fuel pressure regulating control shaft to a "Minimum Fuel Pressure" position to prevent excessive supply of fuel in starting on engines that have such a fuel pressure regulating control shaft normally connected through said linkage to the fuel control shaft for movement therewith.

It will be seen that other features and advantages of the invention are also inherent in the control apparatus in conjunction with the two means set forth above to render same operable, or novel means to simplify respective operations previously accomplished with different structure.

Having now described the invention what I claim as new and desire to secure by Letters Patent, is:

1. Apparatus for controlling the starting of an internal combustion engine, comprising in combination, starting means operable to turn said engine over at a starting speed, fuel control means

movable in one direction to increase supply of fuel to said engine and in an opposite direction to decrease supply of fuel to said engine, governor means responsive to running of said engine at speeds in excess of said starting speed to effect movement of said fuel control means in its said opposite direction, valve means responsive to supply of fluid under pressure to a chamber to terminate operation of said starting means, and means responsive to movement of said fuel control means in its said opposite direction to supply fluid under pressure to said chamber.

2. Apparatus for controlling the starting of an internal combustion engine, comprising in combination, starting control means operable by fluid under pressure to one position to effect application of a starting effort to said engine and upon release of fluid under pressure to effect termination of said effort; a start control pipe; an operator's control device to control supply of fluid under pressure to said start control pipe, an engine fuel control element movable in one direction to a fuel off position and in an opposite direction to a maximum fuel position; a speed governor responsive to speed of operation of said engine and operatively connected to said fuel control element; a relay valve device responsive to release of fluid under pressure from a chamber to establish a fluid pressure supply communication from said start control pipe to said starting control means and responsive to supply of fluid under pressure to said chamber to close said communication and effect release of fluid under pressure from said starting control means, and valve means for supplying fluid under pressure to said chamber upon movement of said fuel control shaft only in said one direction to a position intermediate said fuel off position and said maximum fuel position.

3. Apparatus for controlling the starting of an internal combustion engine, comprising in combination, a fuel supply element for said engine movable in one direction to increase said fuel supply and in an opposite direction to decrease said fuel supply; a fuel pressure regulating element for varying the pressure of said fuel supply, and movable in one direction to increase pressure and in an opposite direction to decrease said pressure; mechanical means connecting said fuel supply element to said fuel pressure regulating element to said fuel pressure regulating element for moving said elements in synchronism; said mechanical means including means for rendering said fuel pressure regulating element and said fuel supply element movable one relative to the other.

4. In combination with an internal combustion engine, a fuel supply element movable in one direction to increase fuel supply and in an opposite direction to decrease said fuel supply; a fuel pressure regulating element for varying the pressure of said fuel supply and movable in one direction to increase said pressure and in an opposite direction to decrease said pressure; connecting means, operable by said fuel supply element to effect movement of said fuel pressure regulating element in synchronism; said connecting means including means for rendering said fuel pressure regulating element and said fuel supply element movable one relative to the other, starting means for said engine, and means operable in synchronism with said starting means for adjusting said fuel pressure regulating element relative to said fuel supply element in its said opposite direction.

5. Apparatus for controlling the starting of an internal combustion engine, comprising in com-

bination, starting means operable to turn said engine over at a starting speed, fuel control means movable in one direction to effect an increase in supply of fuel to said engine and in an opposite direction to effect decrease in supply of fuel to said engine, governor means responsive to running of said engine at speeds in excess of said starting speed to effect movement of said fuel control means in its said opposite direction, means responsive to movement of said fuel control means in its said opposite direction to terminate operation of said starting means, engine fuel pressure regulating means movable to a minimum fuel pressure position, means connecting said fuel control means to said regulating means for adjusting the latter in unison with the former, and comprising means for rendering either adjustable one relative to the other, motor means operable to move said pressure regulating means relative to said fuel control means to said minimum fuel pressure position, and means to effect operation of said starting means and said motor means in unison.

6. Apparatus for controlling the starting of a reversible internal combustion engine having an element movable to a reverse position for rendering the engine operable in its reverse direction, comprising in combination, reversing means operable to shift said element to its reverse position, fuel cut-off means to terminate supply of fuel to said engine, starting means to start said engine, valve means responsive to release of fluid under pressure from a chamber to effect operation of said starting means and responsive to supply of fluid under pressure to said chamber to terminate operation of said starting means, an operator's control device operable to a reverse start position to effect operation of said reversing means, and said fuel cut-off means, means responsive to operation of said reversing means to release fluid under pressure from said chamber, interlock means responsive to turning over of said engine in its reverse direction to terminate operation of said fuel cut-off means, and means responsive to running of said engine on fuel to supply fluid under pressure to said chamber.

7. Apparatus for controlling the starting of a reversible internal combustion engine having an element movable to a reverse position for rendering said engine operable in its reverse direction, comprising in combination, reversing means operable to shift said element to its reverse position, fuel cut-off means to terminate supply of fuel to said engine, starting means to start said engine, a valve device responsive to release of fluid under pressure from a chamber to effect operation of said starting means, and responsive to supply of fluid under pressure to said chamber to terminate operation of said starting means, an operator's control device adjustable to a reverse start position to effect operation of said reversing means and said fuel cut-off means, means responsive to operation of said reversing means to release fluid under pressure from said chamber, interlock means responsive to turning over of said engine in its reverse direction to terminate operation of said fuel cut-off means, fuel limit means responsive to operation of said starting means to limit fuel supply to said engine during starting, and means responsive to running of said engine on fuel to supply fluid under pressure to said chamber and to terminate operation of said fuel limit means.

8. Apparatus for controlling the starting of an internal combustion engine adapted to be turned

over on starting air at a certain speed and to run at speeds above said certain speed on fuel supplied thereto, comprising a fuel control shaft adapted for turning movement in one direction toward and to a fuel off position for decreasing to termination as a limit supply of fuel to said engine, for turning movement in an opposite direction toward and to a maximum fuel position for increasing up to a maximum amount supply of fuel to said engine, and in either said one direction or said opposite direction to an intermediate position to effect supply of fuel to said engine in an amount sufficient to maintain same operating at an idling speed, speed governor means biasing said fuel control shaft toward said maximum fuel position when said engine is being turned over at or below said certain speed and operable in response to subsequent running of said engine on fuel above said certain speed to effect movement of said fuel control shaft to said intermediate position, starting air control means operable to effect supply of starting air to said engine, starting air cut-off means operable to terminate operation of said starting air control means, a depressable stem for operating said starting air cut-off means, and a retractable cam assemblage comprising a lever element secured for turning movement with said fuel control shaft, and a cam element carried by said lever element adapted and arranged to effect depression of said stem substantially upon said shaft attaining its said intermediate position during turning movement of said fuel control shaft only in said one direction.

9. Apparatus for controlling the starting of an internal combustion engine adapted to be turned over on starting air at a certain speed and to run at speeds above said certain speed on fuel supplied thereto, comprising a fuel control shaft adapted for turning movement in one direction toward and to one extreme position for decreasing to termination as a limit supply of fuel to said engine, for turning movement in an opposite direction toward and to an opposite extreme position for increasing up to a maximum amount supply of fuel to said engine, and in either said one direction or said opposite direction to an intermediate position between said one extreme position and said opposite extreme position to effect supply of fuel to said engine in amount sufficient to maintain same operating at its idling speed, speed governor means normally biasing said fuel control shaft toward said opposite extreme position when said engine is being turned over at or below said certain speed and operable in response to subsequent running of said engine on fuel above said certain speed to effect movement of said fuel control shaft to said intermediate position, starting air control means operable to effect supply of starting air to said engine, operator's control means positionable to effect termination of operation of said fuel cut-off means and to effect operation of said starting air control means, starting air cut-off means operable in response to depression of a stem to effect termination of operation of said starting air control means, and a retractable cam assemblage comprising a lever element secured for turning movement with said fuel control shaft; a cam element pivotally mounted on said lever element, a stop element secured to said lever element and disposed in the path of pivotal movement of said cam element, spring means carried by said lever element and arranged to urge said cam element toward a non-retractable position

in engagement with said stop element, said cam element, lever element, stop element and spring means being so arranged as to allow said cam element to be pivotally moved away from said stop element against action of said spring means by engagement with said stem during movement of said fuel control shaft in its said opposite direction from its said one extreme position to its said opposite extreme position and to cause depression of said stem by said cam element in its non-retracted position during subsequent movement of said fuel control shaft from its said opposite extreme position to its said intermediate position.

15. 10. Apparatus for controlling the starting of an internal combustion engine adapted to be turned over for starting at a certain speed and to run on fuel supplied thereto at speeds above said certain speed, comprising a fuel control shaft adapted for turning movement to one extreme position to effect presentation of a maximum flow area through which fuel may flow to said engine and to an opposite extreme position to effect disestablishment of any flow area through which fuel may flow to said engine, speed governor means for effecting movement of said fuel control shaft to said one extreme position when said engine is turning over at or below said certain speed, starting means for said engine, a fuel pressure regulating control shaft adapted for turning movement to one extreme position to effect establishment of a maximum pressure of fuel for supply to the engine and to an opposite extreme position to effect establishment of a minimum pressure of fuel for supply to the engine, a resilient linkage connecting said fuel pressure regulating control shaft to said fuel control shaft in such a manner that movement of said fuel control shaft to its one extreme position urges said fuel pressure regulating control shaft to its one extreme position, motor means operable to overcome action of said fuel control shaft on said fuel pressure regulating control shaft through said resilient linkage to effect movement of the last mentioned shaft to its opposite extreme position, and control means operable to effect operation of said starting means and said motor means.

11. Apparatus for controlling the starting of a reversible internal combustion engine comprising an ahead control pipe, an astern control pipe, an engine reversing motor operable by fluid under pressure from said ahead control pipe to an ahead position and by fluid under pressure from said astern control pipe to an astern position, an operator's control device having an ahead position for effecting supply of fluid under pressure to said ahead control pipe while venting said astern control pipe and an astern position for effecting supply of fluid under pressure to said astern control pipe while venting said ahead control pipe, engine starting means responsive to supply of fluid under pressure thereto to effect application of turning effort to said engine and to release of fluid under pressure therefrom to effect termination of said application, relay valve means responsive to venting of a control chamber to effect supply of fluid under pressure to said starting means and responsive to supply of fluid under pressure to said control chamber to effect release of fluid under pressure from said starting means, a double check valve device having one inlet, another inlet, and also having an outlet which outlet is connected to said control chamber, a

shift interlock device operable upon attainment of said reversing motor to its ahead position to effect establishment of a first communication for connecting said one inlet to said astern control pipe and disestablishment of a second communication for connecting said one inlet to said ahead control pipe and upon attainment of said reversing motor to its astern position to effect establishment of said second communication and disestablishment of said first communication; means for effecting supply of fuel to said engine; and means responsive to running of said engine on fuel to effect supply of fluid under pressure to said other inlet.

12. Apparatus for controlling the starting of an internal combustion engine comprising an ahead control pipe, an astern control pipe, an engine reversing motor operable by fluid under pressure from said ahead control pipe to an ahead position and by fluid under pressure from said astern control pipe to an astern position; an operator's control device having an ahead position for effecting supply of fluid under pressure to said ahead control pipe while venting said astern control pipe and an astern position for effecting supply of fluid under pressure to said astern control pipe while venting said ahead control pipe; engine starting means responsive to supply of fluid under pressure thereto to effect application of turning effort to said engine and to release of fluid under pressure therefrom to effect termination of said application, relay valve means responsive to venting of a control chamber to effect supply of fluid under pressure to said starting means and responsive to supply of fluid under pressure to said control chamber to effect release of fluid under pressure from said starting means; a double check valve device having one inlet, a second inlet, and an outlet connected to said control chamber; a shift interlock device operable upon attainment of said reversing motor to its ahead position to effect establishment of a first communication for connecting said one inlet to said astern control pipe and disestablishment of a second communication for connecting said one inlet to said ahead control pipe and upon attainment of said reversing motor to its astern position to effect establishment of said second communication and disestablishment of said first communication; a fuel control shaft adapted for turning movement to one position to allow for a maximum supply of fuel to said engine and to another position to allow for supply of fuel in amount sufficient for operation of said engine at an idling speed; speed governor means responsive to operation of said engine at or below a certain starting speed to urge said fuel control shaft toward its said one extreme position and to operation of said engine on fuel at speeds above said certain starting speed to effect movement of said fuel control shaft to its said intermediate position, fuel cut-off means responsive to venting of both said ahead control pipe and said astern control pipe to effect movement of said fuel control shaft to its said other extreme position; against action of said speed governor means and responsive to supply of fluid under pressure to either said ahead control pipe or said astern control pipe to release said fuel control shaft; and starting air cut-off means non-responsive to movement of said fuel control shaft from its said one extreme position and responsive to movement of said fuel control shaft from its said one extreme position to its said intermediate position to effect supply of fluid under pressure to said second inlet.

13. Apparatus for controlling the starting of an internal combustion engine comprising; an ahead control pipe, an astern control pipe, an engine reversing motor operable by fluid under pressure from said ahead control pipe to an ahead position and by fluid under pressure from said astern control pipe to an astern position; an operator's control device having an ahead position for effecting supply of fluid under pressure to said ahead control pipe while venting said astern

control pipe; an astern position for effecting supply of fluid under pressure to said astern control pipe while venting said ahead control pipe; and a stop position for effecting venting of both said ahead control pipe and said astern control pipe; engine starting means responsive to supply of fluid under pressure thereto to effect application of turning effort to said engine and to release of fluid under pressure therefrom to effect termination of said application; relay valve means responsive to venting of a control chamber to effect supply of fluid under pressure to said starting means and to supply of fluid under pressure to said control chamber to effect release of fluid under pressure from said starting means; a double check valve device having one inlet, a second inlet, and an outlet connected to said control chamber; a shift interlock device operable upon attainment of said reversing motor to its ahead position to effect establishment of a first communication for connecting said one inlet to said astern control pipe and disestablishment of a second communication for connecting said one inlet to said ahead control pipe and upon attainment of said reversing motor to its astern position to effect establishment of said second communication and disestablishment of said first communication; a fuel control shaft adapted for turning movement to one extreme position to allow for a maximum supply of fuel to said engine; to another extreme position to cause termination of supply of fuel to said engine; and to an intermediate position to allow for supply of fuel in amount sufficient to operate said engine at its idling speed; speed governor means responsive to operation of said engine at or below a certain starting speed to urge said fuel control shaft toward its said one extreme position and to operation of said engine on fuel at speeds above said certain starting speed to effect movement of said fuel control shaft to its said intermediate position, fuel cut-off means responsive to venting of both said ahead control pipe and said astern control pipe to effect movement of said fuel control shaft to its said other extreme position; against action of said speed governor means and responsive to supply of fluid under pressure to either said ahead control pipe or said astern control pipe to release said fuel control shaft; and starting air cut-off means non-responsive to movement of said fuel control shaft from its said one extreme position and responsive to movement of said fuel control shaft from its said one extreme position to its said intermediate position to effect supply of fluid under pressure to said second inlet;

14. Apparatus for controlling the starting of a reversible internal combustion engine comprising an ahead control pipe; an astern control pipe; an engine reversing motor operable by fluid under pressure from said ahead control pipe to an ahead position and by fluid under pressure from said astern control pipe to an astern position; an operator's control device having an ahead position for effecting supply of fluid under pressure to said ahead control pipe while venting said astern control pipe and an astern position for effecting supply of fluid under pressure to said astern control pipe while venting said ahead control pipe; engine starting means responsive to supply of fluid under pressure thereto to effect application of turning effort to said engine and to release of fluid under pressure therefrom to effect termination of said application, relay valve means responsive to venting of a control chamber to

effect supply of fluid under pressure to said starting means and to supply of fluid under pressure to said control chamber to effect release of fluid under pressure from said starting means, a double check valve device having one inlet, a second inlet, and an outlet connected to said control chamber, a shift interlock device operable upon attainment of said reversing motor to its ahead position to effect establishment of a first communication for connecting said one inlet to said astern control pipe and disestablishment of a second communication for connecting said one inlet to said ahead control pipe and upon attainment of said reversing motor to its astern position to effect establishment of said second communication and disestablishment of said first communication, a fuel control shaft adapted for turning movement to one extreme position to allow for a maximum supply of fuel to said engine, to another extreme position to cause termination of supply of fuel to said engine, and to an intermediate position to allow for supply of fuel in amount sufficient to operate said engine at its idling speed, speed governor means responsive to operation of said engine at or below a certain starting speed to urge 25 said fuel control shaft toward its said one ex-

treme position and to operation of said engine on fuel at speeds above said certain starting speed to effect movement of said fuel control shaft to its said intermediate position, fuel cut-off means 5 responsive to venting of both said ahead control pipe and said astern control pipe to effect movement of said fuel control shaft to its said other extreme position against action of said speed governor means and responsive to supply of fluid 10 under pressure to either said ahead control pipe or said astern control pipe to release said fuel control shaft, starting air cut-off means non-responsive to movement of said fuel control shaft from its said other extreme position to its said 15 one extreme position and responsive to movement of said fuel control shaft from its said one extreme position to its said intermediate position to effect supply of fluid under pressure to said second inlet, and means sensitive to direction of 20 operation of said engine to prevent release of said fuel cut-off means until said direction is in accord with position of said engine reversing means.
